PISTON-PORTED VOLUME DISPLACEMENT MEANS ACCOMMODATING MULTIPLE, WORK EFFECTING COMPONENTS

James A. Hardman, 225 West 4th North, Logan, Utah
Filed Dec. 31, 1962, Ser. No. 249,554
35 Claims. (Cl. 310—75)

This is a continuation-in-part of the inventor's application entitled "Fluid Pump System," Serial No. 181,616, filed March 22, 1962, which is now to be abandoned.

The present invention relates to volume displacement apparatus, such as fluid pumps, compressors, fluid-pressure driven motors, motor-generators, engines of internal combustion, steam, and other types, wherein porting is affected through a sweeping-type registry of piston apertures and cylinder ports, and, more particularly, to apparatus of the type described wherein multiple, work affecting components such as plural generators, pumping cylinders, motors, and so forth, may be coupled to or rendered integral parts of the volume displacement apparatus in permissible balanced condition, and, further, wherein the design of the apparatus lends itself to a high degree of reliability in use and to standard manufacturing practices not requiring excessively close machining tolerances.

Principal objects of the present invention are to provide single-acting or double-acting, single or opposed piston, sleeve valve volume displacement means, including liquid pumps, gaseous fluid compressors, engines, motors, and motor generators, wherein multiple, work effecting components such as plural generators, pumping cylinders and motors may be coupled thereto or rendered integral parts thereof in a permissible balanced condition, to provide for simple, vibration-free, high speed, quietly operating volume displacement means; to provide high speed pump and compressor means which can be driven by two, economically constructed motors, or high speed engine means to drive two generators; to provide low stage and high stage compression in each of two cylinders wherein the displacement of the piston rod common to the pistons of both cylinders establishes the volume difference for the two stages of each cylinder; to provide circulating lubricating coolant flow within the piston rod to cool the compression rings associated therewith, and to provide the same for the lubrication and temperature control to all structure, including pistons, requiring the same; to provide balanced power input to and take-off from a piston rod by novel pivot means at the juncture of the piston rod and shuttle structure, and, in connection with the latter, to eliminate imbalance of power input and output resulting from the backlash inequality of gearing tolerances in the drive and take-off means therefor, and to provide balanced input from only one side of a two-rotor (fly-wheel) input; to provide a two-cylinder, double acting piston, pump means wherein four independent stages of compression can be obtained with but two cylinders; to provide a pump, air compressor motor, motor-generator, and engine which, by reason of their sleeve valves, may be driven at very high speeds, speeds which are considerably above those generally considered appropriate and, in connection with compressors, which conventionally used reed and plate valves, for example, can accommodate; to provide alternate means for pivoting the shuttle to the piston rod in the subject volume displacement apparatus construction; to provide optimum heat transfer and dissipation in the present structure by supplying multiple cooling and lubricating channels in the spherical bearings, sockets, and shuttle arm of the shuttle associated therewith, wherein the flow

2

of lubricant flowing in said channels is intermittent, forming successive, pressured lubrication charges which are constantly being replaced at these areas by fresh cooling lubricant; to eliminate excessive, peak loads on piston rod (and other) carrier bearings resulting from the machining deviations from theoretical true values and from motor input differences where motors are employed; to provide self-aligning bearings and pivotal connection between the piston rod and shuttle of the structure so as to permit a resilient bushing, which is incorporated in the structure in one embodiment, to meliorate and distribute such excessive peak loads; to cushion the shock in shuttle and piston rod bearings caused by the backlash of gears when marked power change occurs; to assure equal load on spherical bearings in case of machining irregularities or uneven wear, thus avoiding peak loads beyond the lubricant film strength; to provide relevant embodiments a balanced output (or input) irrespective of the speed ratio of gearing of the two power lanes leading to the motion transforming mechanism of the structure; to provide an adequate, uniform, and continuous main flow of cooling lubricant through the journal and piston rod system of the subject structure, and this notwithstanding the intermittent charges of pressured lubricant at the shuttle's spherical bearings (or rotor journals) which it supplies; to provide volume displacement apparatus of the type described to drive a pair of generators respectively coupled to or included in opposite power lanes of said apparatus and, optionally, to include safety means for cutting off input power to said apparatus when said generators are in objectionable imbalance; to provide volume displacement apparatus of the type described to be driven by a pair of motors in opposite input power lanes leading to or included in said apparatus and, optionally, to include safety means for cutting off input power to said motors when the load of said input power lanes are in objectionable imbalance; to provide a cooling spray to the underside of the crown of a piston and to the inside of its sleeve, to dissipate excessive temperature; to eliminate piston thrust and compression rings in the subject, volume displacement apparatus and, instead provide a high-speed, sleeve effect which utilizes a carbon or other low-friction cylinder liner so as to avoid the presence of lubricant or other foreign matter where the presence of such in the pumped medium is objectionable; to provide circumscribing rings of pressure circulating flow of oil about the piston means of a vacuum pump so as to insure full seal-out of back-pressure, and, optionally, to pressure feed said oil through said cylinder in a circuit having necessary oil-conditioning means if needed, and, further to provide a suitable filter to recover oil entrained in the exhaust; to provide motion transforming structure wherein a compressor cylinder supplies scavenging air to an internal combustion cylinder and this where the pistons of the respective cylinders are common to a single piston rod and, advantageously, are provided scavenging air communication through a piston porting technique.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

FIGURE 1 is a plan view of a representative fluid pump unit and drive means therefor, showing partially in section an assembly of one of two cylinders employed. The cylinder stroke lay-out is shown reduced in scale to the stroke shown in the drive.

FIGURE 2 is a side elevation, partially in section and broken away, showing geared power takeoff from (or power input to) the two rotors of a representative fluid pump or compressor, and further showing an end view of the novel pivotal connections between the shuttle and piston rod.

FIGURE 3 is an enlarged, fragmentary plan view, partially in section at the piston rod, showing a preferred pivotal connection between a representative shuttle and piston rod, as well as coolant flow means extending through the piston rod.

FIGURE 4 is a view, partially in section, and taken along the line 4—4 in FIGURE 3.

FIGURE 5 is a top, fragmentary view, partially in section, of the structure of FIGURE 4, showing principal additional details of the shuttle construction.

FIGURE 6 is a sectioned elevation taken along the line 6—6 in FIGURE 3, showing construction details of the universal cross member with its lubrication channels.

FIGURE 7 is a plan view, partially in section, of alternate universal means for mounting shuttle and push rod; lubricant passages are also shown together with a spherical bearing journaling one arm of the shuttle to its rotor; this figure is similar in orientation to FIGURE 3 but is rotated 90° in a counter-clockwise direction with respect thereto.

FIGURE 8 is a view of the cross member only, shown in FIGURE 7, which is transposed in elevation to the right of FIGURE 7.

FIGURE 9 is a section of the cross member, taken on line 9—9 in FIGURE 7, with the side tie member removed and oil channels shown.

FIGURE 10 is a view, shown principally in section, and taken along the line 10—10 in FIGURE 7 when the piston rod is at mid-stroke position, of a representative rotor, spherical bearing and shuttle arm, showing the novel coolant and lubrication mechanism of the spherical bearing and shuttle arm.

FIGURE 11 is a view, taken along the line 11—11 in FIGURE 7 and rotated 90° in a clockwise direction, for convenience of illustration, of a respective one of the removable side clamp members shown in the assembly of FIGURE 7.

FIGURE 12 illustrates yet another alternate means, shown principally in plan, similar to FIGURE 3, of pivotal connection between the piston rod and shuttle.

FIGURE 13 is a cross section taken along the line 13—13 in FIGURE 12.

FIGURE 14 is a detail, rotated 90° with respect to FIGURE 13, of one of the rotation coupling plugs, two of which are shown in FIGURE 13.

FIGURE 15 is a view, taken along the line 15—15 in FIGURE 12 and partially in section, showing the configuration of the top structure of FIGURE 12.

FIGURE 16 is a view taken along the line 16—16 in FIGURE 12.

FIGURE 17 is a fragmentary elevation, broken away and partially sectioned for convenience of illustration, of a volume displacement apparatus (pump or compressor, here) having a single, single-acting piston, according to one embodiment of the invention.

FIG. 18 is an enlarged, fragmentary section of the piston of FIGURE 17, showing the construction and attachment of the piston rod to the piston.

FIGURE 19 is a transverse, sectional view of a configurated spacer used in connection with exhaust and intake conduit attachment flanges in FIGURE 17.

FIGURE 20 illustrates the structure of FIGURE 17 wherein the same is modified to include a pair of opposed pistons operating in respective cylinders, and is in reduced scale.

FIGURE 21 illustrates a plan view of an embodiment of the invention wherein the same takes the form of a two-stage air compressor.

FIGURE 22 illustrates a partial cylinder in which the piston rod and oil wiping gland portray the use of a low friction lubricating sleeve, such as a carbon sleeve, interposed between the piston and cylinder wall.

FIGURE 23 represents a partial cylinder in section with oil seal rings provided to seal the piston for vacuum pumping.

FIGURE 24 is an elevation of a double acting air cooled cylinder useable in the present invention.

FIGURE 25 is a fragmentary bottom view of the structure of FIGURE 24 and illustrates a conduit mounted on one of the port groups.

FIGURE 26 is a plan view, broken away for convenience of illustration, of the cylinder in FIGURE 24, showing in dotted lines a representing porting for a cylinder.

FIGURE 27 portrays in elevation a double-acting piston partially in section to show the piston rod mounting flanges and intake and exhaust apertures.

FIGURE 28 is an end view of the piston of FIGURE 27 with the medial partition plate in place to show the attachment orifices.

FIGURE 29 is a representation of the port groups on one side of a liquid cooled cylinder, showing also the O-ring seals, water jackets and special sleeve designed to meet requirements of contamination-free, pumped medium.

FIGURE 30 is a fragmentary bottom view of the cylinder of FIGURE 29, showing mounting holes and port manifold in place with attachments.

FIGURE 31 is a top view, broken away for convenience of illustration, of the cylinder in FIGURE 29, showing in dotted lines the structure and location of cylinder ports and O-ring seals for the water jacket sleeve employed.

FIGURE 32 is a plan view, partially in section, of a motor-generator unit, to show the assembly of two double-acting cylinders and two generators as well as the piston rod seals and guides thereof.

FIGURE 33 is an enlarged fragmentary section of one of the pistons of FIGURE 32, showing in section the piston rod assembly therein and the oil cooling circuit employed.

FIGURE 34 is a section, taken at 34—34 in FIGURE 32, showing the cylinder port conduit locations with respect to the cylinder.

FIGURE 35 is an enlarged elevation view of one of the double-acting pistons of FIGURE 32 and showing the fluid apertures for displacement control.

FIGURE 36 is a plan view largely in section of an engine generator unit wherein one cylinder provides a scavenging pump for the internal combustion cylinder of the opposite side, to operate two balanced output generators.

FIGURE 37 is a section enlargement of the power piston of the engine of FIGURE 36, showing the piston and the piston rod assembly.

FIGURE 38 is a diagrammatic roll-out of the air cylinder shown in FIGURE 36, with a roll-out of the piston superimposed thereon to portray porting functions throughout piston travel, and is fragmentary.

FIGURE 39 is an elevation view of a single-acting piston, showing multiple porting for large, high-speed pistons.

FIGURE 40 is a typical cylinder roll-out accommodating the piston of FIGURE 39, showing multiple porting facility for large volume flow.

FIGURES 41—44 illustrate a roll-out of the piston in FIGURE 39 superimposed over a roll-out of the cylinder in FIGURE 40 to show four sequential positions, in that order, of the piston apertures and their relationship to the cylinder ports of a single-acting, air-compressor cylinder of large volume as in FIGURE 17.

FIGURES 45—48 depict piston roll-outs superimposed over-cylinder roll-outs at four sequential positions (12

o'clock, 9 o'clock, 6 o'clock, and 3 o'clock) of the double-acting air compressor cylinder and piston of FIGURES 24-28, which is also suitable for use in FIGURE 1.

FIGURES 49-52 are overlays, at piston positions 12 o'clock, 9 o'clock, 6 o'clock, and 3 o'clock, respectively, of a roll-out of a representative piston over a representative cylinder (as in FIGURES 32-35), wherein groups of intake and exhaust apertures sequentially register over respective, single cylinder ports, as desired, and will apply to liquid pumps and fluid-driven motors.

FIGURE 53 is an elevation of a piston according to yet another form of the invention, wherein reduced piston length is accomplished by having a single piston skirt, with the skirt accommodating both intake and exhaust apertures.

FIGURE 54 is a roll-out of a cylinder accommodating the piston of FIGURE 53.

FIGURES 55-58 are overlays, at piston positions 12 o'clock, 9 o'clock, 6 o'clock, and 3 o'clock, respectively, of a roll-out of the piston of FIGURE 53 over a roll-out of the cylinder of FIGURE 54, indicating the times and positions when piston apertures approach, enter, and leave registry of respective cylinder ports.

In FIGURE 1 central housing 10 is provided with carrier bearing plates 11 and 11', and a pair of power generating sources 12 and 12' such as electric motors are respectively mounted thereto and to the central housing 10 by bolts 13 and 13' the ends only of which are shown. Each of the carrier bearing plates 11 and 11' is provided with respective seats 14 and 14' for seating the respective carrier bearings 15 and 15'. Rotor members 16 and 16' are each integrally provided with hubs 17 and 17' (the latter of which is supplied with gear teeth) and also are axially affixed in 90° transverse relationship to shafts 18 and 18', of power sources 12 and 12', which preferably extend therewithin in a pressed or other fixed relationship. The hubs 17 and 17', in a preferred embodiment of the invention, engage the inner races of carrier bearings 15 and 15' so as to secure the same within the respective bearing seats 14 and 14'. Each of the motor shafts 18 and 18' is provided with respective axial, stub apertures 19 and 19' and with respective, radial apertures (one or more in number), designated as 20 and 20' communicating therewith. Apertures 19, 19', 20 and 20' comprise lubricant passageways which proceed through rotor members 16 and 16' to certain bearings and other structure as will be hereinafter described.

The shafts 18 and 18' with their respective rotors 16 and 16' have nominally common axes of rotation coincident with axis 21 and nominally transverse to the piston rod axis and intersecting therewith. The rotors 16 and 16' are rotated in opposite directions and journal a shuttle 22. As shall be hereinafter explained in detail, the shuttle 22 is universally journaled thereto by spherical bearings seated within respective rotors 16 and 16' at nominally equally eccentrically situated sockets of the rotors, such that upon the opposing rotation of the two rotor members 16 and 16', the shuttle 22 will be simultaneously translated back and forth in the direction A and A' and also will be caused to be continuously rotationally displaced about the axis of piston rod 23 and at right angles thereto. We shall now turn our attention to a discussion of the cylinder and stuffing gland structure, and related structure associated with piston rod 23. Air cooled cylinders 27 and 27' are mounted via their base flanges 28 and 28' to respective flanges 29 and 29', of stuffing gland members 30 and 30', and to the central housing 10 by a plurality of stud and nut attachments 31 and 31'. While the cylinder pair is shown as a pair of air-cooled cylinders having fins 32 and 32', it will be obvious that other types of cylinder constructions are possible. Each cylinder will be supplied with wall orifices 33, 34, 35 and 36 which receive respective conduits 37, 38, 39 and 40. These orifices and conduits are all outlet or exhaust orifices and conduits; intake orifices and conduits are

delineated as 42' and 43', 44' and 45', respectively. It will be mentioned at this juncture that the two cylinder constructions, as well as their respective piston constructions, are substantially identical. The cylinder constructions at the upper half of the figure are given regular numbers where as that of the lower portion of the figure are given prime ("') numbers.

Cooling chamber cover 46 is mounted by cap screws or other attachments 47 to the cylinder member 48, of cylinder 27, and includes internally threaded bores 49 and 50 for receiving conduits 51 and 52. Inverted cup member 53 is likewise secured to cylinder member 48 by attachments 47 and defines with cooling chamber cover 46 a cooling chamber 54 which, with the flow of coolant therewithin, serves to cool the respective cylinder head of each of the two-cylinders used. There is need for a favorably heat-exchange relationship at cooling chamber 54 to conduct from the cylinder area the heat which is generated by compression occurring within the cylinders in the course of the reciprocation of piston rod 23. Again, the cylinder constructions of both halves of the structure are functionally identical and so only one-half will be described in detail. The above remains true, of course, even though functional requirements may dictate differences in displacement volumes of the two cylinders for various operating requirements.

It will be seen hereinafter that for certain design reasons and particularly in the area of multi-stage compressors, the piston rod diameter dimensions together with piston and cylinder dimensions may be altered and varied as desired for any one of a number of reasons. Notwithstanding these, however, it is conceived that the general structural design features, excluding possible alterations in dimensions, will obtain as that shown in the upper half of FIGURE 1.

Plate 55 is secured in place by machine screws 56 (one only being shown), and the latter are threaded into stuffing gland members 30. Plate 55 thus retains the spherical bearing socket halves 57 and 58 against washer-type spacers 59 and sleeve-type spacers 60. Disposed between the latter spacers, as shown, are conventional compression rings 61 and conventional oil wiper rings 62. Both sets of rings 61 and 62 are retained in place by conventional, self-contained annular springs, with the compression rings 61 serving to maintain compression and for pressure during the back-stroke of the respective piston, and the oil wiper rings 62 serve to preclude the passage of lubricant on the outer surface of the piston rod 23 into area 63. The purpose, of course, for keeping lubricant out of the area 63 is to preclude the necessity in certain applications of filtering lubricant from the compressed air or other compressed or pumped materials, for certain applications, and, in addition, to preclude general loss of lubricant from the lubricating system of the structure.

Bearing 64 is of a spherical, self-aligning type, and its function, together with the other characteristics of its mounting within the stuffing gland assembly are more fully described in the inventor's co-pending United States patent application entitled, "Two Piston Sleeve Port Engine," Serial No. 119,485, filed June 26, 1961, now abandoned, which is incorporated herein by way of reference and fully made a part hereof.

The central housing 10 comprises, in effect, a sump of lubricant reservoir in proximity with which is disposed a conventional oil pump 65 adapted to receive oil or other lubricant at intake 66. The pump 65 will include a shaft 67 to which gear 68 is pinned or otherwise axially secured. The pump gear 68 will be disposed in mesh with gear teeth provided on hub 17' of rotor member 16' so that the pump will be driven thereby by the power source used. The lubrication circuit is shown somewhat in schematic form, with phantom lines indicating general conduit routing. One orifice 69 of pump 65 will be coupled by conduit 70 to a respective stationary collar 71 circumscribing motor shafts 18'. Collars 71 will of course be

supplied with a radial aperture 72 which is disposed in communication with radial aperture 20' of motor shaft 18' by annular groove 72'. This construction is identical with respect to the motor shaft 18; hence, the latter will not be described in detail except for the fact that T 73 and conduit 74 provide this latter result upon the coupling of T 73 to another pump output 69" (69" corresponding to 69 for the remaining cylinder). Another conduit 77 is threaded into stuffing gland member 30 at passageway 78, the latter taking the form of a radial bore communicating with return passageway 79, the two passageways forming communication with each other via annular groove 80. Annular groove 80 may be machined into the stuffing gland member 30 before stuffing gland plate 81" is welded or otherwise affixed thereto to cover the same.

Conduit 52 leads from threaded boss 50 directly to and is attached at the orifice 81 of central housing 10. The same holds true for conduit 52' and its interconnection with the return orifice 81' in FIGURE 1. Thus, it will be observed that the lubricant pump 65 supplies lubricant under pressure to the rotor members 16 and 16' via passageways 19' and 20', 19 and 20, and so forth and supplies lubricant as a coolant for the stuffing gland 30 via passageway 78, and so forth and additionally supplies a coolant via conduits 51 and 52 to the cooling chambers 54 of a representative cylinder. Further, in being in communication with the interior of central housing 10, the lubricant is also supplied to piston rod shaft 23 so that an appropriate lubricating film may be supplied this shaft as the same reverses and rotates with the shuttle, within spherical bearing 64 (on both sides of shuttle 22).

As shall be seen with more particularity hereinafter, it shall be mentioned at this point that a journaling pin 82 is provided within the shuttle 22 to connect the shuttle 22 to piston rod 23. Again, this will be described with more particularity hereinafter.

At this juncture it is important to note the structure at the extremities of piston rod 23. The piston rod 23 is provided with a pair of tapered ends (one being shown) as at 83 to which is keyed as at 84 to a mounting flange member 85. The opposite ends of piston rod 23 are threaded as at 86 and receive a pair of securement nuts 87 and 88. Piston 89 proper includes conventional rings 90, with the head portion thereof at 91 being riveted at 92 to mounting flange member 85 and also to an upper steel ring 93. Mounting flange member 85 and also to an upper steel ring 93. Mounting flange member 85 will also preferably be made of steel so that when the piston is fabricated from aluminum, for example, distortion and other wear problems will be eliminated and a secure mounting assured.

It should be noticed in passing that for maintenance purposes it is possible that the cup member 53 may be removed, the nuts 87 and 88 removed so that the piston rod 23 can be released from its connection with piston 89 and the mounting flange member 85.

In FIGURE 2 is shown a pair of carrier bearing cover plates 94 and 94' which seat bearings 15 and 15' as before, which are similar to the carrier bearing plates 11 and 11' of FIGURE 1, but which this time are now provided with lubricant passageways 95.

Instead of being motor shafts, the shafts 96 and 96' will generally be stub shafts, preferably, and there will be mounted thereon in a splined or other keyed mounting a respective pinion gear 97 on each of the shafts 96 and 96'. Each of the gears 97 (only one being shown) will be disposed in mesh with a ring gear 98 which is secured by cap screws or other attachments 99, or other means, to a disc 100, the latter being integral with or otherwise secured to drive shaft 101.

End bells 102 and 103 are secured to the central housing 10 in FIGURE 2, and outboard journaling bearings 104 and 105 journal the shafts 96 and 96' and have their covers bolted to end bells 102 and 103. Bolted or otherwise affixed to the end bells 102 and 103 and also the central housing 10 is a side bell structure 106 which is pro-

vided with a journaling boss 107 suitably interiorly shouldered at 108 and 109 for receiving carrier bearings 110 and 111, the latter journaling drive shaft 101. As indicated in FIGURE 2 the drive shaft 101 is coupled to a source of power 112 adapted to rotate the same. If desired, a cover inspection plate 113 may be secured to the central housing 10 and be affixed thereto by means of bolts or other attachments 114. A shoulder 249 abuts the inner race of bearing 110 to hold the bearing securely in position. Correspondingly, at the opposite end of shaft 101 there is supplied a washer 115 and a pair of nuts 116 and 117 which thread onto shaft 101 and which retain the bearings 110 and 111 in place. Preferably, a cap 118 will be threaded into the boss 107, as shown, to preclude oil leakage, the entrance of foreign matter, and so forth.

At this juncture there will be discussed the relative merits of the two respective approaches taken in FIGURES 1 and 2 for driving motor members 16 and 16'. It will be noted in FIGURE 1 that two prime movers such as electric motors of oppositely revolving character are directly connected by the respective motor shafts to the two rotor members 16 and 16'. On the other hand, in FIGURE 2 is illustrated a single mover such as an electric motor 112, which is used to drive a single input shaft 101 and, consequently, and by reason of the inclusion of a ring gear 98 and a pair of pinions 97, the two rotors 16 and 16' which are caused to rotate in opposite directions. One obvious advantage of the FIGURE 2 structure over that shown in FIGURE 1 is that but a single power source is needed; further, various speed change ratios are obtainable in FIGURE 2. Concerning ourselves with general principles, it should be noted that the motors 12 and 12' in FIGURE 1 should be substantially identical in characteristics and synchronized; however, it will be understood and will be shown hereinafter that there are certain compensating features which are built into the shuttle 22, piston rod 23 combination which compensate for any unbalance which may exist due to unbalance or lack of synchronization between the two motors 12 and 12'. In FIGURE 2, however, it will be noted that since gears are employed directly within the structure that an automatic speed reduction is obtainable so that the rotors 16 and 16' may be driven at a different speed from that of the input shaft 101. It will be shown hereinafter that the shuttle 22, piston rod 23 combination even in this context will compensate for backlash and mounting errors as well as other existing machining tolerances present in the system which are excessive.

Consideration will now be turned to FIGURES 3 through 6 wherein is shown the detailed structure of the shuttle 22 and piston rod 23 together with their interconnecting, mounting means.

Shuttle 22 includes a shuttle member 118 having a pair of shuttle arms 119 and 120. The construction of the shuttle arms 119 and 120 are identical and hence only one will be discussed. It should be mentioned at this juncture that the shuttle member 118 is hollow but is provided with closed ends 121 (one being shown). Each of the shuttle arms 119 and 120 includes a band or annular perforate region 122 which is characterized by a plurality of oil passageways 123 arranged somewhat like a band around the periphery of shuttle arm 119. These passageways 123 all communicate from the exterior surface of each of the shuttle arms 119 and 120 to the respective hollow interior 124 and 125 of the shuttle member 118. Disposed on each arm is a slight relief recess 126 over which the journaling spherical ball of the shuttle arm, hereinafter described, overrides so that a shoulder will not be developed on the respective arms.

Centrally disposed through shuttle 22 is piston rod 23 which, as shown in FIGURE 3, is disposed within and held in place by resilient bushing 127 the operation of which will be discussed fully hereinafter. This bushing 127 is seated within aperture 128 of the shuttle member 118 at the enlarged central portion 129 thereof. A

seat 130 may be supplied the resilient bushing 127 as required.

An oil return tube 131 is illustrated in section centrally in FIGURE 5. In actually a pair of oil return tubes 131 are employed, and each has a threaded end 132 which threads into a respective locating aperture 133 of piston rod 23. This construction is identical on both sides of shuttle 22. The ends of the oil return tubes 131 are held in central positions by perforate or other type, washer-like retainers 131' which are adapted to pass lubricant transversely therethrough. Communicating with the interior of each oil return tube 131 is a respective aperture 134 which is blinded off but which communicates with lateral aperture 135 leading outwardly of piston rod 23 and interior of the central housing 10. Again, the construction is the same on both sides of shuttle 22 so that there will also be an aperture 135' as shown. It will be noted, however, that the resilient bushing 127 and seat therefor are located only on one side of the shuttle 22.

Further detail of the structure is illustrated in FIGURE 6 wherein is seen a cross member 136 which is affixed to a piston rod 23 by means of journaling pin 137. It will be noted that there is some clearance between piston rod 23 and the cross member 136. This clearance merely by way of example will be of the order of, say, $\frac{10}{1000}$ to $\frac{3}{1000}$ of an inch, thereby permitting sufficient movement of piston rod 23 about the axis of pin 137 for certain compensating purposes as will be explained later.

In FIGURES 3 and 6 are illustrated journaling bosses 138 which are designed to receive a journal cap 139 to be secured thereto by capscrews 140. It will be noted that the apertures 143 and 144 are blinded off by setscrews 145 and 146. These apertures are not in mutual intercommunication. Also will be noted the apertures 147 and 148 which are disposed in communication between the apertures 141 and 142, respectively, of pin 137 and also with their respective apertures 149. Apertures 149 in FIGURE 6 registers with aperture 150 (see also FIGURE 4) of the shuttle member 118 which in turn registers with the interior 124 of the shuttle member. Both sides of shuttle 22 will be designed similarly; hence, but one side is shown in detail and in section.

There are thus two circuits for oil flow as regards the shuttle, piston rod combination. One of these circuits will now be discussed and the remaining circuit will be understood as being identical, only associated with the opposite side of the shuttle and the opposite extremity of the piston rod. Oil will be received by rotor member 16 as hereinbefore described and is routed to the spherical bearing journal (hereinafter described in detail) which slideably receives in a universal connection the shuttle arm 119 of shuttle 22. Oil enters the plurality of apertures or passageways 123 in FIGURES 5 to proceed down the interior passageway 125 (similar to 124 at the left side of shuttle member 118), and thence toward the center of the shuttle to its aperture or passageway 150 (the remaining passageway 150 associated with the remaining arm being shown in FIGURE 6). The oil lubricant, hence, proceeds, as shown in FIGURE 4, down the passageway 150 of shuttle member 118, and aperture 152 of cross member 136, to proceed outwardly therefrom via aperture 149 (see FIGURES 4 and 6) and upwardly therefrom via passageway 147 and passageways 141 and 144 to the passageway 153 into an associated half of the piston rod 23. Oil proceeds thence between the inner wall of piston rod 23 and the outer wall of oil return tube 131 to double back near the extremity of the piston rod, thence back through the associated oil return tube 131. On completing the return route through oil return tube 131 the oil is discharged from a metering aperture 135 into the oil bath of the central housing 10. An identical lubricating circuit will be understood in connection with the remaining half of the piston rod and the remaining shuttle arm 120.

It is to be noted in passing that the registration of apertures 149, 150, and 152, for example, in FIGURE 4 admit the presence of oil to the journaling surfaces of the cross member 136. To take advantage of this fact 5 there may be provided annular grooves 155, 156, and 157 as shown in FIGURE 6. An additional groove 155 (not shown) will likewise be supplied the identical, remaining left-hand arm of the cross member 136 in FIGURE 6.

10 Structure which may be used which is alternate to that illustrated in FIGURES 3 through 6 is shown in FIGURES 12 through 16. In the drawings and particularly in FIGURE 13 is illustrated a piston rod 158, identical in all respects as in the case of piston rod 23, excepting 15 that in the present piston rod there will be supplied an enlarged ball portion 159 disposed centrally of the piston rod and including therewith threaded fittings 160 and 161 for receiving the threaded end portions 162 and 163 of the oil return lines 131. As before, the flow of oil 20 will proceed outwardly to the piston rod extremities between oil return line 131 and piston rod 158 and, subsequently, will return back to the center of the structure through the two oil return lines 131. Passageways 164, 165, and 166 and 167 are supplied as indicated so 25 that the oil returning back to the center of the structure through oil return lines 131 may spill out into the oil bath at the central housing 10 of the structure (not shown). This alternate shuttle member 168 includes apertures 169 and 170 for receiving rotation-coupling 30 plugs 171 serving to couple the rotation of the shuttle to the piston rod about the piston rod's axis but which will permit rotational displacements of the piston rod at the ball area about the two remaining axes thereof.

35 Plugs 171 are cylindrical in nature but have keying ends 172 which cooperate with and engage the slots 173 of ball portion 159. The slots 173 are both substantially identical in form and are diametrically opposite with respect to each other. Interior grooves 174 are supplied for receiving respective retainer rings 175 which retain 40 the plugs 171 in position and serve as limit stops for plugs 171 so as to prevent their outward travel. It will be noted in connection with FIGURE 13 that the contour of the key ends at 172 of the plugs are convex, matching the concave configuration of slots 173. Other 45 configurations are possible. However, it should be mentioned that whatever the configuration of these parts, the same should be such that some clearance may be had between the two at the inner extremities of the plugs 171, thereby permitting slight rotational displacement of 50 the piston rod 158 about axis A which is in the line of sight of the viewer and perpendicular to the plane of the paper. Correspondingly, the journal fitting of the two plugs 171 within their respective apertures 170 enable rotational adjustments of piston rod 158 about axis B. 55 However, the slots will be designed so that there is a relatively close fit between the slots of ball portion 159 and the key ends 172 of plugs 171. Thus, the rotation of shuttle member 168 about axis C will produce, and without appreciable tolerance of movement, the simultaneous rotation of piston rod 158 so as to accomplish 60 the porting of the piston cylinder combination.

To complete the structure there is illustrated a cap 65 176 which is secured to the remainder of the shuttle by means of capscrews 177. Bosses 178 receive plugs 171 as shown in FIGURES 13 and 16. Finally, the enlarged central portion 179 of shuttle 168 accommodates capscrews 177 and the cap plate or cover 176.

It will be noted in both embodiments of the shuttle, piston rod combination constructions thus far explained 70 that the universal connections thereof are respectively remote from the intersection of the axis of the piston rod and shuttle along the piston rod axis. Though rigid connection is possible, as shown in FIGURE 17, universal connection between the piston rod and the shuttle 75 is preferred so as to compensate for machine or other

errors whereby the axes of the piston rod and the shuttle do not, strictly speaking, intersect for all positions of the former with respect to the latter during the operation of the structure.

In FIGURE 10 a typical structure is shown illustrating the spherical journaling of the shuttle to its representative rotor of the structure. Rotor shaft 18 is provided and includes plural, intersecting oil passageways 179 and 180 which intersect each other. Rotor 16 is keyed to the shaft 10 by key 181. Securement is made fast by the means of washer 182 and nut 183. Rotor member 16 is provided with an aperture 184 and an enlarged seat 185 for bearing 187. Bearing ball 188 is spherically journaled within the socket halves 186 and includes apertures 189, 190, 191 and 192 which are representative ones of two mutually askew sets of passageways preferably originating at the ball periphery in parallel respective ring patterns.

Additional, and likewise radially askew apertures may be provided if needed. Interior annular grooves 193 and 194 are also supplied and additional ones of these grooves may be employed as necessary. It is to be pointed out that in practice the number of apertures 189 and 190 will be quite great and will be drilled into the ball 188 at different angles so that in fact the ball is perforated at many points. All of these apertures, however, are preferably directed to come in communication with those annular grooves 193 and 194 which are used. The outer extremities of apertures 189, 190, 191, and 192 must be relatively close together, however, so these will not sweep outside of the limits of the socket halves of the bearing.

Particular attention is to be called to this area of discussion. It will be noted that the socket halves 186 have adjacent chamfered edges which delineate a groove 195 traversing peripherally about the ball 188. It will be important to note that some of the passageways 89 and 90 will be in communication with groove 189; in such event, clearly there will always be oil pressure feeds exerted against the surface of the shuttle arm 196, of shuttle member 197, at annular grooves 193, 194; similarly, all other passageways 189 and 190 at their outer ends will supply pressure heads against the inside friction surfaces of socket halves 186. The slideable interaction of the shuttle arms with their respective ball journals 188, when the system is put into operation, will create a simultaneous translation and rotation of the shuttle arms within their respective balls 188. This in turn requires a high degree of lubrication and, more importantly, a great amount of heat exchange so that the heat generated thereat resulting from friction on both the inside and outside of the bearing 188 may be carried away very rapidly. It is important to note that the plurality of shuttle arm member apertures 198 (similar as to location and function of those previously discussed) sweep along and over the pressure head grooves 193 and 194 so that the apertures 198 will progressively be supplied with pressure heads of lubricant. (Of course, it will be understood that the positioning of all of the apertures 198 within arm 196 of our shuttle member 197 will be such that they will not sweep out of the journal area of the ball 180.) Hence, what is occurring is a continuous general flow of lubricating coolant through the spherical journal and the shuttle member 197, this by virtue of intermittent lubricant surges through the respective apertures 198 which are swept progressively so that at all times some of these apertures are conducting oil and that all remaining apertures are progressively employed, in supplying a multiplicity of pressurized segments of constantly renewing coolant, in successive relationship, to conduct the lubricant accordingly and to lubricate the journal.

To complete the lubricating and coolant structure of the spherical journal, annular groove 199 is supplied in

the rotor 16 at seat 185 which communicates with radial bores 200 communicating with groove 189.

At this juncture it is important to note that because of the motion transforming character of the structure there will persist a continuing, sliding friction contact between both inner and outer bearing surfaces of the ball 188 and the associated components, namely, shuttle 197 and, owing to the movement of the ball, in the ball socket halves 186, which friction contact produces a great amount of heat. In other contexts where a spherical bearing is conventionally employed, such double friction action on the inside and outside of the ball does not occur; hence, the housing of a conventional journal is sufficient to carry away the heat that is generated by bore friction. In the present situation the presence of lubricating passageways through the socket halves 186 at the socket half, ball juncture, and through the ball 188 itself and the shuttle 197 journaled therewithin affords continuous flow of oil therethrough which will keep the entire structure at the bearings 188 very cool, thereby precluding the malfunction attendant to excessive heat production at journals. If other types of articulative journals for rotor, shuttle intercoupling are used, such as those illustrated in the inventor's copending application entitled "Two Piston Sleeve Port Engine" before referenced, then lubricant may be passed through the journals employed in a manner similar to that above described with reference to the spherical bearing journals.

In FIGURE 11 is shown in elevation a detail of a side journaling member 201, the same being provided with apertures 202 and 203, a bronze sleeve 204 and a tightening bolt 205 which serves to clamp the structure at 202 to the shuttle 197. A pair of these journaling clamps 201 is shown in FIGURE 7 which illustrates the mounting thereof to shuttle 197 (similar to shuttle 22). Bronze bushing 204 of each of the journaling members 201 receives a respective arm 206, 207 of cross member 208. A detail of the cross member 208 is illustrated in section in FIGURE 9. The same includes the sectional view of two additional arms 209 and 210, at right angle to the former, and includes intersecting apertures 212 and 212' for receiving piston rod 23 and pin 213, respectively. The latter is supplied with oil apertures 214, and 215, 216 and 217, and diameter apertures 218 and 219 communicate with their respective apertures 214 and 215, 216 and 217, respectively, thereby supplying continuous oil passageways through the pin 213. Additionally, askew apertures 220 and 221 are supplied in the cross and these respectively communicate with apertures 222 and 223 thereof. Thus, lubricating oil will proceed through the structure in FIGURE 7, beginning at the ball 188, and from thence will proceed through apertures 198 into the interior 224 of the associated shuttle arm and, therefrom, will proceed through radial apertures 225 and through journaling clamp apertures 226 and subsequently through bronze bushing aperture 227 and radial cross aperture 228 to enter passageway 229 which is blinded off by set-screw 230. From passageway 229 the lubricant proceeds through apertures 222 (see FIGURES 7 and 9), up passageway 220 and through aperture 214, through passageway 218 and out aperture 216 to be urged into the piston rod at a point between the inner piston rod wall and the return tubes 31. The position of these have been heretofore described in connection with the structure shown in FIGURE 3.

As shown in FIGURE 9 there will be provided an aperture 231 in the shuttle 197 for admitting piston rod 23. Some clearance, of the order of $10/1000$ to $20/1000$ of an inch, for example, will exist between the shuttle and piston rod 23. As before, metered passageways 232 and 233 will be present to conduct oil returning from the oil return tubes 131 to the oil bath within housing 10 proper. It is to be noted that there is a universal coupling in the provision of cross member 208 and associated equipment to the right of the shuttle member 197

in FIGURE 7. Again, it is important to note that cross member 208 is removed somewhat from the intersection of the intersecting axes of piston rod 23 and shuttle 197. As to the rotational displacement possible, it will be noted that the arms 206 and 207 are journaled within respective bronze bushings 204 of the respective journaling clamps 201 so that rotational displacements of the piston rod 23 about an axis in the plane of the paper and perpendicular to the axis of the piston rod, i.e. the axis of setscrew 230, is possible. Correspondingly, and owing to the provision of the pin 213, there is enabled a rotational displacement about the axis of pin 213 by the piston rod 23 so that, considering the piston rod 23 as a reference, slight deviations of the shuttle 197 from its plane perpendicular to the piston rod will be compensated for by the universal joint existing at pin 213 and arms 207 and 206 with their journals 204.

As has been indicated heretofore in connection with the operation of the equipment, it has been noted that for pumps (and, indeed, for all types of equipment including engines employing a motion transforming system incorporating a reciprocating piston rod and a revolving shuttle to which oppositely revolving rotors are connected) that it is important to compensate for slight misalignments which may exist in connection with rotor fabrication and mounting, journal mounts therefor, spherical bearing mounts thereof accommodating the reciprocating shuttle, variation in distance of the rotor from the axis of the piston rod, slight differences in the rotor themselves, and so forth. This the present invention accomplishes by virtue of a universal joint connection at the shuttle, piston rod mounting so that such inequalities are not manifested by or result in excessive bearing loads, stresses and strains, or other difficulties. The universal connection structure illustrated in the respective embodiments of FIGURES 1 and 3 through 6, of the embodiments illustrated in FIGURES 12-16 or of the additional embodiment illustrated in FIGURES 7-11 all illustrate a particular type of universal mount which may be used. Conceivably, other types of universal couplings interconnecting the shuttle with the piston rod may be employed. In all of the above embodiments shown, however, it is important that the universal connection be removed longitudinally of the piston rod, somewhat, from the intersection or proximity point of the axes of the shuttle and the piston rod as intended by the design.

While the designs described in connection with the universal joint coupling between the shuttle 22 and piston rod 23, herein taught, are deemed preferably, it is conceivable that even simpler forms of universal coupling between the two members may be accomplished, this for example where the journals employed have sufficient play to permit universal adjustment even though the journal, piston rod, and shuttle axes may not quite intersect. However, whatever the form of universal intercoupling, the present invention comprehends that in fact a universal joint or self adjusting connection persists in the region of the shuttle and piston rod coupling so that the same may be self-correcting to compensate for any errors in alignment and manufacture as heretofore described.

In all cases of universal mounting as above described, however, it is necessary that play, in the sense of journal looseness, between shuttle and piston rod shall be absent from piston rod rotation and reciprocation. It will be apparent that if slack or play is encountered in the bearings in the above connection or if the design were constructed in such a manner that looseness or play were permitted in the journals, as regards thereto, then, inasmuch as the operation of the machine produces high speeds of reciprocating, oscillatory motions in both the rotating and the reciprocating functions, the bearings would soon break down under severe loading and fail to provide the necessary acceptable construction. Such

also would destroy the lubricating pressures required. It is for this reason that the axes of universal mounting of piston rod and shuttle have been spaced from the proximity point of the piston rod and shuttle axis in order that the structure may sustain stress reversal and reversal of forces when the equipment is in motion.

Other advantages in the utilization of present structure in pump of other contexts reside in the manner in which the spherical bearings of motion transforming devices of the type described are relieved of heat build-up at these spherical journals. The novel manner and means by which such is accomplished has been heretofore described and is very important.

Likewise important is the lubricant pumping system employed wherein lubrication and coolant, preferably in the form of a single fluid substance, may be used for heat exchange purposes and also to lubricate all moving parts at their several journals.

Further advantages have been found in connection with cooling, as by the lubricant contained in central housing 10, the stuffing gland structure associated with a double acting reciprocating piston rod with this novel motion transforming device.

Continuing with the consideration of the stuffing gland assembly 24 as in FIGURE 1, it is noted that what is present in the structure is a double-acting piston and cylinder construction, on both sides of the power transformer structure, wherein the upstroke will produce simultaneously an intake beneath double skirt piston 89 and a compression above piston 89 and, correspondingly, during the downstroke, an intake will occur above piston 89 and a compression beneath the piston 89. Owing to the fact that the area or volume beneath the piston is utilized in a compression stroke, an adiabatic rise in temperature and a marked production of heat attendant thereto will occur at the sealing structure (stuffing gland assembly 24) and particularly at stuffing gland member 30. This marked increase in heat will affect the journaling of the piston rod within the stuffing gland deleteriously so that if heat were not removed satisfactorily malfunction can well occur, plus the production of excessive temperature in materials being pumped or compressed. It is to avoid this that the stuffing gland is cooled by the passage of circulating coolant within member 30 as hereinbefore explained. Additionally, a similar operation takes place in the region of cooling chamber 54 at the crown of the cylinder. By providing a circulating coolant through the cooling chamber 54 in FIGURE 1, increases in heat which occur there by virtue of compression during the upstroke of the piston will be carried away therefrom and into the general body of lubricating coolant within the central housing 10. Further, since the piston rod 23 in FIGURE 1 is in the compression chamber beneath piston 89 and interior of the piston's lower skirt 240 it is appropriate, as is accomplished by this invention, that cooling the piston rods be provided for. This is done, as has been explained, by the provision of lubricant outwardly between the piston rod wall and return line 131 disposed therein and the subsequent routing of the lubricant back through line 131 to be drained therefrom into the general body of lubricant within central housing 10.

Likewise to be noted is a provision of a complete circulatory system for lubricating and cooling all of the moving, journaled parts of the system including the shuttle and piston rod; this is accomplished even through a universal joint connection is provided at the piston rod, shuttle juncture.

As to each of the pistons 89, themselves, see FIGURE 1, the same includes piston head 238, plural piston rings 90 conventionally mounted thereto, and upper and lower piston skirts 239 and 240 integral with piston head 238. Piston skirt wall apertures 234, 235 and 236, and 237 are provided and comprise exhaust apertures. 75 Adapted for predetermined, selective, and progressive

registration therewith are cylinder exhaust ports 241, 242, 243, and 244. Correspondingly, both of the piston skirts 239 and 240 of each piston are provided with intake wall apertures 247 and 248, respectively, and intake ports 245 and 246 of each of the cylinders 27 (and 27') are provided for registration therewith in accordance with the translation and simultaneously produced rotation of the pistons 89 as results from the similar movement of the reciprocating piston rod (i.e. 23). While but single intake ports and piston apertures are needed for each skirt of each of the respective pistons, it is highly desired that diametrically opposite exhaust apertures and ports be supplied to accommodate balance and exhaust or outbow from the compressed volumes of each piston half.

As to port timing relationships, location of cylinder ports and piston apertures as above described, reference is made to the inventor's United States Patent No. 2,828,906, entitled "Engine," which is hereby incorporated herein and fully made a part of the disclosure hereof.

In passing it will be noted that the piston rings 90 are in sealing relationship both ways, that is, both with respect to the volume above the piston head 238 and the volume therebeneath. It is to be noted by virtue of the unique construction in the present invention that the rings 90 will not pass over any port. In the condition shown in FIGURE 1, the maximum position for intake is achieved beneath the piston head 238 whereas exhaust conditions is shown for the upper volume which was immediately previously compressed.

Finally, it is to be mentioned that the present invention is ideally suited to high speed equipment and, in particular, the present invention, among other things affords a means by which a high speed reciprocating rod may be lubricated and cooled in a highly acceptable manner.

We shall now consider some general observations.

In the case of the FIGURE 2 embodiment it will be seen that power source 112 drives the two rotors 16 and 16' by balanced and timed power lanes which are driven by a single shaft 101 and disc 100 thereof and the ring gear 98 affixed thereto. The pinions 97 and 97' which are splined to their respective shafts 96 and 96' intermesh with the common ring gear 98 and are of equal diameter and uniform tooth type so that the rotors 16 and 16' to which they are respectively coupled are driven in a uniform and timed manner. (This discussion of course neglects considerations which may be due to appreciable gear wear through use, or poor adjustments.)

In the FIGURE 2 embodiment, then, it has been found that a universal connection of one of the three characters described, or conceivably other universal joints of equivalent nature, when disposed at the shuttle piston rod juncture or proximate thereto will compensate for machining irregularities, manufacturing tolerances, and so forth, of the equipment. Further, additional factors such as bearing wear, adjustment factors and rework, and other factors involved are taken care by such universal joint connections.

Where, instead of the single input drive of FIGURE 2, a pair of power sources 12 and 12' such as electric motors are employed to drive the rotors 16 and 16' in opposite directions as is shown in FIGURE 1, then additional factors are introduced into the operating characteristics of the system. These factors are of course directly related to such innate differences between the two power sources 12 and 12' as may be present. It is common knowledge that it is theoretically impossible to match motors, for example, precisely in all the characteristics such as torque, speed, fly wheel effect, inertia, timing relationships, adjustment and installation differences, feed back and magnetic flux interplay where the two motors are approximately disposed, and so forth. Exact synchronization and preservation of equivalent timing relationships are difficult even in the case of synchronized motors, when used. Therefore, the inven-

tor has found it highly desirable to employ, in addition to a universal joint connection at the shuttle and piston rod area or juncture, the resilient bushing 127, shown merely by way of example in FIGURE 3. It will be understood that the resilient bushing construction forms a resilient filler, in effect, between the piston rod 23 and the shuttle 22 therefor, with the center of the resilient bushing 127 being spaced from and disposed as remotely as practicable from the universal connection between the piston rod 22 and shuttle 23, by way of example. The resilient bushing construction may be utilized also in the other embodiments of the invention as shown for example in FIGURES 12 through 16 and FIGURES 7 through 11. (Merely by way of convenience of illustration, such a resilient bushing is not shown in these latter two embodiments.) It will be understood that the same may be present in other universal connection means as in the same or a similar construction as shown in FIGURE 3.

It is to be noted that the resilient bushing 127 tends to restore and retain the piston rod 23, shuttle 22 structure in true theoretical position, however, will lend sufficient yield to the structure that the universal connection structure before described can take effect so as to compensate for the various error factors which may be present including deviation from equal eccentricity in which the rotor means articulatedly receives and journals the shuttle. Further, the bushing 127 will tend to compensate for error sources in the two prime movers 12 and 12' which should be matched as to produce the revolvment of their respective rotors in angular velocities so far as possible. Additionally, the bushing 127 compensates for torsional lag in the shaft couplings to the rotors 16 and 16', for member flexion, housing yield, and so forth. There will, of course, be advantage in using the bushing construction even in the case of the FIGURE 2 embodiment, as above outlined.

Models constructed in the past have generally been found to be quite free running at some portion of the complete cycle. It often occurs, however, at other points as the rotors revolved that considerable binding will occur. As a matter of fact, when altogether familiar with the designs, an operator will often assemble all bearings and gears with very slight clearance in order to verify the accuracy of the machining practices. A study of the location of the bind and of the function of the piston rod, shuttle and rotors, will often readily indicate the irregular parts.

Let it be assumed then that a rigid cross is provided at the shuttle and push rod and, upon assembly, there appears a bind somewhere in the stroke. The bearing means sustaining this load would not, in all probability, impose equal loads on the two power sources, especially if one spherical bearing were overloaded. This tends to unbalance the drive torque and slow one motor down. At another opposite point, however, this loss must be restored where slack is expended. This creates a very severe "fighting" effect caused by the great amount of inertia in the two drives.

As this resultant builds up it becomes sharper and more instantaneous until often failure or looseness occurs in some of the journals.

When failure of appropriate journal tolerances occurs, then the entire lubrication system is interrupted.

The resilient bushing has the effect of avoiding these peak loads and provides a constant force of restoration to the functional requirements of the motion transformer construction.

In FIGURE 17 motors 12 and 12' have their respective output shafts 18 and 18' secured to rotors 16 and 16' (substantially identical to those of FIGURE 1) in a manner identical to that shown in FIGURE 1. Carrier bearings 15 and 15' are provided as in FIGURE 1. A central housing 255 is provided and is secured at its end flanges to motors 12 and 12' by tie-rods 263 and 263', 264, and

264' and by nuts 265 and 265'. The motor shafts 18 and 18' will be held on a common center line. Electrical conduit 328 is supplied for electrical leads 329 leading to motors 12 and 12'. The motors 12 and 12' may simply be connected in electrical parallel with respect to input leads 329 and, if desired, a differential relay 331 may be included in junction box 330 and connected to the motor leads and the input leads 329 in a conventional manner so as to insure that power to the motors 12 and 12' will be cut off when the motors experience a predetermined imbalance in load for safety purposes. This will be described more fully hereinafter.

Arrows A and B indicate the direction of rotation of rotors 16 and 16'. It is obvious that the direction of rotation of these motor shafts can be reversed. It is only essential that there be a mutual opposite revolvement with respect to rotation so that the shuttle action, hereinafter described, may take place.

Central housing 255 includes an upstanding, journaled mounting boss 256 provided with an orifice 332 providing communication between areas 333 and 334.

Secured to the annular, journal-mounting boss 256 is a shouldered support flange 257, securing therefore being made by cap screws 261. Bearing socket member 258 is attached to support flange 257 and includes threaded mounting apertures 258' for receiving cap screw 262. The latter secures the support flange 257 to bearing socket member 258. It will be noted that the member 258 is provided with the interior shoulder 259. This seats filler socket member 260, and tight securing of the bearing socket is assured by the slight spacing at 262' which permits cap screws 262 to perform the tight socket fitting intended. Self aligning guide bearing 267 is disposed as a ball in a ball and socket self-aligning connection with the socket 335 comprising members 258 and 260. Guide bearing 267 is provided with an interior axial bore 336 which serves as a guide journal for piston rod 250. Support flange 257 is provided with a medial aperture 337 which permits oil or other lubricant to drain from the journal formed by guide bearing 267 and piston rod 250, and oil drippings, for example, therefrom drip down into the area 333 which may form either a dry or filled sump. Piston rod 250 is interiorly hollow and includes a closed end 273, a medial boss 269 and a flared end 285. Shuttle 251 is closed ended at 279 and 280 as by welch plugs (not shown), for example, and is hollow at oil passageway areas 281 and 282. Passageways 283 and 284 provide communication between the former, respectively, and oil tubes 272 and 268 which conduct the oil to the piston medial partition 291, permitting the conduction of lubricant therefrom along the inside of the hollow tubes 272 and 268, back through the piston rod 250 exterior of the supply to proceed to the lubricating system via apertures 270 and 271.

Threaded seats 276 and 277 communicate with the aforementioned passageways 283 and 284, respectively, and provide for the threaded seating of tubes 268 and 272. The remaining end of tube 272 is secured by means of a washer-type spacer 274 which is supplied with annular spacer orifices 275. See the lower third of FIGURE 17.

The remaining extremity of oil tube 268 is retained in position by circular boss 293 apertured at 294, of the medial partition member 291 of the piston assembly about to be described.

Piston halves 287 and 288 are secured together by attachments 290 and to annular flange 338 of the flared end 285 of piston rod 250. Piston halves 287 and 288 are, in general character, cup-configured, apertured at the base, and with medial partition member 291 forming a medial partition of the composite, double-acting piston assembly. This piston assembly shall be referred to generically as piston 339. Piston aperture means 295 are supplied in the piston walls of the piston 339, and their various configurations will be described hereinafter.

Cylinder 296 is provided with an attachment flange 297 and the latter is secured to central housing 255 by stud attachments 590 and nuts 590'. Cylinder 296 also includes annular water jacket flange 591 and bosses 298 and 299. For cooling purposes, there is preferred the inclusion of water jacket 301 which is sealed to cylinder 296 by O-ring 307. O-rings 592 and 593 provide water seals for the various cylinder bosses indicated at 298 and 299.

As indicated, the water jacket 301 includes plural bosses, i.e., at 302, 303, 304, and 305. Suitable O-ring sealing means are indicated by the presence of O-ring seals as at 592. Annular grooves 306, 593 accommodate O-ring seals; additionally, there is supplied an annular groove 317 where the upper O-ring 318 is installed. The water jacket 325 may be unitary as shown or comprise segmented rings covering any desired segment of the cylinder. The water sealing means may be designed to accommodate the type of water jacket used.

A cylinder head 315 is secured to cylinder 296 by cap screws 595. The cylinder head 315 includes an enlarged depending portion 319, and the cylinder head construction is shown to include a general V-configured coolant channel 321 which affords communication between water jacket bosses 304 and 305. For convenience of fabrication and also cleaning, plugs 323 are provided to cap off the upper extremities of the coolant channel, and are threaded into bores 596 and 597 for this purpose.

The cylinder head 315 also includes porting relief areas 320 which facilitates the exhaust operation of the pumped medium.

Conduits 308 and 309, 310 and 311, 312 and 313 are respectively connected to the various ports illustrated, and are aided in their securing by cap configurated washers 324, a sectional detail of which is illustrated in FIGURE 19, and locking nuts 314. The configuration of FIGURE 17 is preferably in vertical, upstanding disposition.

FIGURE 20 is a plan in reduced scale, similar to FIGURE 17, but illustrating the structure as substantially horizontal and that composite cylinders 325 may be disposed on both sides of central housing 255, thus, in FIGURE 20 the lower-end journaling of piston rod 250 in FIGURE 17 may be eliminated, an additional access aperture 598 supplied corresponding to and diametrically disposed in the housing 255 with respect to aperture 598 in FIGURE 17, so that the two cylinders 325, similar to the cylinder 325 shown in FIGURE 17, may be accommodated. The housing thus modified will be designated as 255'.

The operating characteristics of the structure shown in FIGURES 17 through 20, as thus far described, are as follows: Input electrical lead 329 supply power to both motors 12 and 12'. A junction box 330 provides conventional parallel connections for the two motors with respect to leads 329 and may or may not indicate a differential relay of conventional manufacture interposed between the input leads 329, leads 329', and 329" leading to each of the respective motors 12 and 12'. Again, where included, differential relay 331 will simply lead to the purpose of cutting-off input power to the two motors when the loads thereof are in a predetermined imbalance. Self aligning guide bearing 267 provides a guide journal for the piston rod 250. The mounting feet 249 and 249' to motors 12 and 12' indicate that a preferable position of the structure is such that the piston rod 250 reciprocates along a line which is vertical to the ground plane at 599. This is not to be understood as restricting the structure to vertical piston rod movement. Indeed, the structure of FIGURE 20, in addition to that shown in FIGURE 17 may well be used wherein the equipment lies in a substantially horizontal plane. However, vertical reciprocation of the piston rod 250 in FIGURE 17 embodiment is indeed

preferable where single cylinder arrangements in FIGURE 17 are employed.

Large amounts of heat generated at the piston cylinder area during operation of the compressor of FIGURE 17 are carried away by the circulating system, not shown, of the water or other liquid coolant which circulates through jacket 301 and, particularly, which circulates through the V-configured coolant channel in cylinder head 315. It will be noted that this channel 321 in cylinder head 315 permeates almost the entire cylinder head depth so that a highly effective heat-exchange relationship occurs between the coolant circulated through the cylinder head and compression chamber areas which are defined by upper piston half 287 and the surface, interior of this piston half, of cylinder head 315. This includes lowermost head area 590.

The rotors 16 and 16' in FIGURE 17 are substantially identical to those illustrated in FIGURE 1, with the possible exception of slight outer surface dissimilarity in contour.

Bearing balls 252 and 252' will be identical to the bearing balls 188 in FIGURE 7. The bearing balls will also include lubricant communicating passages which sweep across the series of apertures in the shuttle 251 in a manner substantially identical to that shown in FIGURES 7 and 10 in connection with bearing ball 188 and bearing socket 186. Lubricant will be pressure fed through rotors 16 and 16' in FIGURE 17 through the bearing balls 252 and 252' to proceed through the shuttle apertures of shuttle 251 to passageways 281 and 282. Coolant proceeds through these passageways and through their adjacent passageways 283 and 284 to enter into and proceed outwardly of tubes 268 and 272. On leaving the outer extremity of tube 268, coolant will pass through apertures 294 to enter into the area between tube 268 and the inner wall of piston rod 25. From thence coolant will proceed outwardly through metered return orifice 270 to the interior of housing 255. In a similar manner lubricant will proceed to the outer extremity through tube 272 and will double back through apertures 275 of spacer 274, to proceed from thence out of metered aperture 271. A suitable pump return, not shown, will be interposed between the housing 255 and the rotors 18 and 18' in a manner identical, conceivably, to the coolant circuit shown in FIGURE 1 and FIGURE 32.

The porting of the piston and cylinder construction of FIGURE 17, in connection with conduit 310 and 311 and piston aperture means 295 will be discussed hereinafter. It suffices to say at this juncture that the structure of FIGURE 17 is intended as a two-motor drive type compressor having but one single acting cylinder which is intended for use with compressibles only when ports, as shown, are employed. Conduits 312 and 313 simply refer to the conduit of the liquid coolant system employed. No specific lubrication system need be shown in connection with guide bearing 267. It is sufficient to rely upon the splash within housing 255 to lubricate the guide bearing 267 within socket 335 and also to supply a thin oil film upon the outer surface of piston rod 250 which reciprocates within bore 336 of bearing 267.

The structure shown in FIGURE 21 is similar, substantially, to that illustrated in FIGURE 20, that is, with the structure employing a pair of cylinders of different sizes and designated 296 and 296'. Absent this difference in size, the cylinders 296 and 296' will be identical in character to each other and to that shown in FIGURE 17, with the exception that the cylinders in FIGURE 21 are air-cooled whereas those illustrated in FIGURE 17 are cooled by water or other liquid coolant. Arrows A and B, again, illustrate that the rotation of the rotors respectively coupled to motors 12 and 12' are in the opposite directions relative to each other. A pair of mounts 341 are respectively affixed to motors 12 and 12' for mounting purposes, by way of example, and journal fan counter shafts (which revolve in opposite directions) 342'

and 343', respectively. Air cooling shrouds 344 and 345 are fixedly disposed with respect to the remainder of the structure as by attachments 346 and serve to direct air directly across the outer surfaces of the cylinders 296 and 296'. Conduit 347 and 348 are coupled in communication with cylinders 296 and 296', and corresponding conduit 349 and 350 are diametrically situated in the under side with respect to the former two conduits and are directly connected in communication with appropriate apertures of the cylinders 296 (exhaust) and 296' (intake). Conduits 347-350 are each supplied with respective pluralities of fins for cooling purposes. Thus, air or other compressible material is initially compressed in cylinder 296, the larger of the two cylinders, and from thence will be transmitted to cylinders 296' for further compression. This general system of feeding from one cylinder to another in an integrated system is known as multiple staging in air compressors. The fans 342 and 343 are appropriately fixed to provide maximum air cooling of the fins of cylinder assembly 296 and 296'. For maximum cooling effect, the conduit 347, 348, 349, and 350 will be interposed between housing 255' and respective shrouds 344 and 345.

FIGURE 22 illustrates a piston and cylinder construction which may be used to advantage in both the present and other contexts. Cylinder 351, shown in fragmentary view only, is somewhat similar to that illustrated in FIGURE 17. It includes cylinder ports 352 and breather orifices 353 and 354. Cylinder head 355 is removably affixed to cylinder 351 by cap screws or other means 356. Piston 358 is affixed by suitable means to piston rod 359, and the latter is provided with suitable oil-ring type stuffing gland means 360, of conventional design, which wipes piston rod 359 and isolates the piston and cylinder area from the housing and oil supply of the apparatus. Should any excess oil or oil vapor be carried through stuffing gland 360 to area 361 beneath piston 358, then breather orifices 353 and 354 will perform the function of expelling vapors beneath piston 358 to insure that such vapors do not proceed between piston 358 and cylinder 351 to the area above the piston and/or proceed in through cylinder ports 352, so that any oil present will not proceed outwardly with the pumped medium.

Of importance is the inclusion of a special lubricant sleeve such as a carbon sleeve 362, or other low friction cylinder liner, which is pressed or cemented or otherwise secured into cylinder 351 and seated against shoulders 363 and 364 of cylinder 351 and cylinder head 355, respective, and which includes ports 352' which coincide and thus register with the port means 352 of cylinder 351. An explanation for the inclusion of this sleeve is as follows. In conventional crank and connecting rod type air compressors considerable side thrust is imposed upon a piston working within the cylinder as the piston proceeds up and down within the cylinder. This side thrust is due to the inclusion in the design, of the conventional crank and connecting rods which are journaled on the crank and pinned to the piston.

The common practice today in compressors is to include segmented carbon piston rings backed by suitable expanding spring means, but with the provision of the piston wall directly contacting the cylinder wall so that side thrust may be accommodated. The soft nature of carbon would render the inclusion of a carbon sleeve in such a piston cylinder construction inappropriate and inadvisable where any piston skirt side thrust is experienced. Piston rings would also be very injurious to a carbon sleeve. By virtue of the nature of reciprocation in the engine and compressor design of the present invention, side thrust is eliminated. There is no connecting rod and crank action to impose side thrust on the piston skirt.

In the present invention, and by virtue of the nature of

the directly driven reciprocation of the pistons within their respective cylinders, carbon sleeves may be used since no side thrust is present and no piston rings are scraping on the cylinder wall. Wear, hence, is minimal and the carbon sleeve 362 or other suitable material capable of sustaining its physical characteristics and not scoring is advantageously included. Such inclusion eliminates the necessity for any additional lubricant since the carbon sleeve itself will provide a reduced coefficient of friction between the piston and the effective cylinder to that desired and, in addition, will not sluff off. The configuration of FIGURE 22 is ideal where oil-free air or other media is to be obtained from the pumping unit. This oil-free quality of the pumping action of the present pump or compressor is useful particularly in the preparation of food stuffs, *medicaments*, and other materials wherein oil contamination is objectionable.

FIGURE 23 illustrates piston and cylinder structure which may be used in any desired application of the present invention and which is particularly suited for vacuum work. In FIGURE 23 the new cylinder 365 includes any desired number of annular oil recess grooves such as 366 and 367 which communicate with lubricant passageways 368, 369, 370 and 371. Conduits 372 and 373 are connected to recess groove 367. Other conduits, 694, 695, are connected to recess groove 366 in the cylinder wall. These grooves 366 and 367 supply annular rings of oil under pressure (from a conventional pumping source, see P) directly against the piston 358. These oil rings will be disposed such that the piston aperture 374 and any other apertures associated therewith will not pass over the oil rings. It is to be noted that by use of these oil rings under pressure, mechanical rings can be dispensed with in the piston construction and yet high vacuum work accommodated. Further, the oil rings 366 and 367 complete the vacuum seal so that high vacuums can be maintained. As a result of the rapid heat transfer and close fit (.0005 per inch of diameter as lapped clearance, for example) of the piston diameter and cylinder bore, together with the oil seal provided, oil which is "pumped over," as a result of oil-flooding the pump can be recovered in the usual manner as is conventional in the operation of oil-submerged vacuum pumps.

Specifically, lubricant pumping system LPS in FIGURE 23 includes pump P, pressure relief valve PRV, sump SU, and conduit 372, 373, 694, 695, and 696, connected as shown, for supplying a complete circulatory system for lubricating the piston 358' within cylinder 365 at annular oil grooves 366, 367 and sealing the same against back-pressure leakage, for vacuum pump work. Though simply a lubricant pressure head at the piston-cylinder junction, at grooves 366, 367, could be used, it is deemed preferable to have a fully circulating system, as shown, so that any air leaking by the piston and proceeding to the oil sealed area will be entrained in the circulating oil thereat and be carried to the settling tank-type sump SU, through pressure relief valve PRV, so that the air may be freed from the oil thereat and the circulated oil thereby conditioned to be free of air before recirculation to the cylinder-piston juncture. This function keeps the oil seal effective between the piston and cylinder.

It is conventional practice to "flood" vacuum pumps in oil of special character to maintain seal; to recapture such oil as may be entrained in the exhaust, a suitable filter F of conventional design, operatively disposed over and in communication with cylinder exhaust port means 698, and drainback DB to sump SU may be supplied the exhaust circuit.

In FIGURES 24, 25, and 26 is illustrated a representative cylinder construction, termed cylinder 375, which is usable in accordance with the principles of the present invention wherein a double-acting air-cooled cylinder is called for. Cylinder 375 includes a multiplicity of mutually spaced, air-cooled fins 376 and, in addition, includes the base mounting flange 377 which is readily attachable

to the central housing in FIGURES 1, 17, 21 and 36 such as housing 255 in FIGURE 17. Integral with medial ones of said cooling fins is a conduit mounting pad 378 which provides and, in fact, defines the cylinder intake passageway 379. Disposed through the cylinder wall and communicating with cylinder intake passageway 379 is cylinder intake port means 380 which comprises a plurality of ports 381 of either the same or of varying sizes. It is to be understood that the cylinder 375 of FIGURE 24 will have an additional passageway 379 and an additional and duplicate set of cylinder intake port means 380 on the opposite side of the cylinder, see FIGURE 26, and which will be disposed in the same relationship, at 180° rotation of the cylinder, as that indicated in FIGURE 24.

Cylinder intake passageway 379 forms a large volume passageway. It would be undesirable to have a direct communication of this entire unitary area directly upon the piston enclosed within cylinder 375. This is because of the distortion that might take place upon generation of heat within the cylinder during the operation thereof which would distort the cylinder wall and interrupt the seal which is intended to be present. Special care in this connection must be exercised since no piston rings are used. It has been found desirable to include a multiplicity of small apertures, designated ports 381, so as to handle a large intake volume and to provide intake through substantially the full 180° intake stroke. There is an advantageous relationship among the several ports 381 and, in connection with the porting diagram hereinafter disclosed, this will be discussed. It must be remembered at this point that the equipment is designed for high speed operation. It should be pointed out, further, that the employment of several openings, ports 381, renders the cylinder construction easy to machine and to hone as small port holes are present, and this without chancing wall distortion or honing stone damage. Tapped holes 382 are provided in pad 378 to accommodate attachment of the conduit mounting plate 386, for external connection of the air conduit 385, FIGURE 25. Cylinder exhaust ports 383 and 384, FIGURE 24, likewise provide communication through the cylinder to the piston area. Cylinder ports 383 and 384 will be spaced apart in degree, a magnitude which is related to the magnitude of piston sweep within the cylinder and the spacing selected for maximum port seal between the top and bottom displacement volumes. In one embodiment of the invention, and as shall be hereinafter described in connection with the porting diagrams, the angular separation between exhaust ports 383 and 384 will approximate 113° in magnitude, see FIGURE 26. This is a representative example for a given piston sweep. For other piston sweeps other magnitudes of angular separation between the cylinder ports 383 and 384 will apply.

FIGURE 25 illustrates a representative one-half of the cylinder construction explained wherein conduit 385 has its associated mounting flange 386 affixed to mounting pad 378 by means of attachments 387. Circle 388 merely defines the interior wall of cylinder 375.

In FIGURES 27 and 28 is illustrated a double-acting piston 389 which is designed for incorporation and positioning in cylinder 375. Piston 389 includes piston halves 390 and 391 which are both cupped and flanged so as to be secured end-to-end, and provided with a common medial aperture 392 which supplies access for the particular piston rod employed. Medial partition member 291, see FIGURE 17, forms the upper portion of the piston rod assembly, i.e., of piston rod 250, is affixed to the back-to-back piston halves 390 and 391 by means of attachments 290 (see FIGURE 17) and their passage through apertures 393 of the medial partition member 291, and through aligned apertures supplied in the piston halves 390 and 391. It will be understood that the construction of the piston 389 in FIGURES 27 and 28, is identical to that shown in FIGURES 17 and 18, with the exception that in FIGURE 17 the piston apertures are disposed only above the medial partition 291, whereas in

FIGURES 27 and 28 there are piston apertures which are disposed above and below partition member 291. Piston aperture means 394 comprises plural apertures 395, 396, 397, and 398, the former pair being disposed above partition member 291 and the latter pair being disposed beneath the partition member 291. Further, piston apertures 395 and 396 are diametrically opposed so as to avoid piston thrust caused by the differential side pressure exerted on the piston if the holes were imbalanced. Additionally, the piston apertures 398 and 397 are diametrically opposed with respect to each other. It may be pointed out that other apertures may be disposed above and below partition member 291; however, such apertures as are additionally used should be "balanced" with the remaining apertures on this side of the partition. Some reasons for the inclusion of more than one aperture both above and below medial partition member 291 are: The ease in grinding which is assisted by having stones wide enough to lap the holes and avoid interrupted cut.

As to the cylinder 375, again, machining is facilitated by the inclusion of plural ports. But most important is the fact that, not only does the port plurality 381 of the cylinder 375 accommodate a large and continuing inflow of air during the intake part of the cycle, but also, where a double-acting construction is present as in FIGURES 25 and 27, the ports 381 may be so constructed and arranged that some of the ports themselves may serve a double function. In this connection, attention is called to the arcuate lines A and B, FIGURE 24. As will be more fully pointed out hereinafter, assume that during upstroke the aperture 398 in FIGURE 27 of the piston 389 is proceeding upwardly in its sweep along the arcuate line B (see FIGURES 24 and 48). During this course of travel then, as piston aperture 398 proceeds upwardly along its arcuate course (B) successively greater amounts of air or other media will be drawn into the piston below medial partition 291. This is on the intake portion of the stroke relative to piston half 391. At this time, i.e., during this portion of the stroke, the piston aperture 396 will be passing over dead or closed cylinder area so as to ultimately come in registry with cylinder exhaust port 384. During the return portion of the stroke there will be a sweeping of the piston aperture 396 along arcuate line A (FIGURES 24 and 47) over the series of ports provided along this path A. During this portion of the stroke the piston aperture 398 will be passing over closed area along the cylinder wall to finally exhaust at port 383. So much of the porting phenomenon has been explained at this juncture to indicate that three of the piston ports 381 (381A-381C in FIGURE 45), see also in FIGURE 24, are seen to be double-acting, i.e., serve as intake ports for both piston halves 390 and 391. The extremity ports are simply single-acting for the respective piston halves 390 and 391. It will be understood, of course, that the foregoing represents merely one piston, cylinder arrangement, relative to porting, which may be utilized as one of a number of porting patterns available to accomplish desired results. FIGURES 24-27 indicate what the inventor wishes to term a long coupled design wherein the cylinder is lengthened to accommodate the double-acting porting desired. A representative short coupled arrangement is discussed hereinafter.

FIGURES 29-31 indicate an alternate piston and cylinder construction, substantially identical to that illustrated in FIGURES 24 through 27, but which this time accommodates alternate cooling means in the form of a water jacket 399 having multiple O-ring seals 400, 401, and 402, and also 403 seated in respective grooves 404, 405, 406, and 407. Carbon 362' when included, is shouldered at 409 within cylinder 408 at one extremity and adapted for seating by a suitable cylinder head 408' attached to cylinder 408 by attachments 409'. The configuration of the cylinder head and attachments is generally illustrated in FIGURES 17 and 22, and this physical construction

may be identical, if desired, in the FIGURE 29 embodiment. The water jacket sleeve 399 and cylinder 408 are assembled in the new, novel manner, may be termed cylinder assembly 375' so that a tight seal may be obtained by the O-ring seals. Configurated spacer 500 is employed to accommodate the attachment of flange 501, of the conduit 502 to the water jacket 399 which is disposed over passageway 379 (see also FIGURE 24). The cylinder porting illustrated in FIGURE 29 is shown to be identical to that seen in FIGURE 24. Again, other types of specific porting arrangements may be employed as will be hereinafter pointed out. The configuration of configurated spacer 500 in FIGURE 30 may be substantially identical to that shown in section in FIGURE 19 relative to the FIGURE 17 embodiment. Of interest with respect to FIGURE 29 is the fact that the water jacket sleeve 399 will slip over the O-rings mentioned and the cylinder 408. When mounting bolts 409' are installed, the water jacket sleeve 399 is prohibited by these bolts from springing away from the cylinder. Further, the pressure of the bolt attachment will tend to keep the water jacket from springing away from the O-ring seals, this by virtue of water pressure against the O-rings in their respective grooves. But this water pressure simply serves to increase the seal so that no leaks are chanced to occur around the port areas.

In FIGURES 32-35 is illustrated a fluid-driven motor-generator, or a fluid driven motor coupled to a pair of generators as balanced driven components, whichever way the same is thought of. While a pair of oppositely driven generators (with respect to generator rotors) are shown, it will be understood that the motor and shuttle portion of the equipment may be used to drive any desired load or series of loads (of respective components). Further, the equipment may be direct driven, as shown, or the same may be driven by gear means or belt drives as in FIGURE 2. A pair of cylinders 504 are indicated and are respectively mounted to carrier bearing housings 509. These carrier bearing housings 509 are mounted to opposite sides of central housing 510 and communicate with opposing apertures 511 thereof. Attachments 512, 513, 514, and 515 complete the attachment of respective cylinders 504 with their respective carrier bearing housings 509 to the central housing 510. Base mounting frame 516 extends on both sides of central housing 510 and runs underneath the same to support the entire machine. Generators 517 and 518 are attached by bolt or other suitable attachments 519 and 520 to the base mounting frame 516, and each is provided with respective end bearing carrier cones 521 associated with the respective generators 517 and 518 and are mounted by bolts 522 through respective inner bearing plates 523 to central housing 510. Conduit 524 leading from oil pump 525 is connected by conventional means to oil feed collar 526, the same being retained against bushing 527 by locking collar 528. Inner bearing plate 523 receives the bushing 527 which journals generator shafts 529 and 530. The outer extremities of respective generator shafts 529 and 530 are retained by bushings 531 disposed in respective bushing mounts 532, the latter secured to base mounting frame 516. The construction is identical for both generators 517 and 518. The rotor 533 in each generator 517 and 518 is keyed to its respective shaft 529 and 530 by key 534. Preferably, the rotors 533 of the respective generators 517 and 518 are additionally secured to their respective shafts 529 and 530 by means of tangent bolts 535. This technique is conventional for heavy equipment. Respective bushings 536 (only one being shown) makes up the respective shafts 529 and 530 and abut respective generator rotors 533 and shoulder at 537 against respective bearing carrier cones 521.

As for lubrication, the oil pump 525 in feeding oil via lines 524 to collars 526 supplies a ring of oil at each groove 538 which communicates with respective radial passageways 539 leading to axial passageways 540 for

the two sides of the equipment. Passageway 540 directly feeds into rotor 16 and has pressure feed therethrough and through spherical bearings 188 and shuttle 118 into piston rod 541 as hereinbefore explained.

Piston rod 541 will be identical to piston rod 23 in FIGURE 1 excepting for the outward extremity portions thereof. Piston rod 541 includes identical extremity structure at opposite extremities thereof, and a representative extremity is shown in FIGURE 33. Piston rod 541 is tapered at 542 and keyed at this region to the piston rod 541 by means of key 543 to piston mounting flange 544. Medial partition member 545, similar to member 291 in FIGURE 18, is secured by cap screws 546 to piston halves 547 and 548, which can be identical to piston halves 287 and 288 in FIGURE 17 excepting for porting as will hereinafter be explained. The piston halves 547 and 548 form respective upper and lower portions of the composite piston 579. Piston rod 541 is threaded at area 550 that receives locking nut 551 which, on pressing on retainer 552 seats the piston mounting flange 544. Piston rod 541 includes a conical seat 553 which receives conical nut 554, and the latter is shouldered at 555. An oil flow control plate 556 is self-spring loaded and engages at its inner and outer peripheral extremities the nut 554 and lower annular portion 557 of medial partition member 545. Oil control plate 556 is provided with plural apertures 558 and 558' which communicate with the spacing between piston rod 541 and respective tubes 559. Respective tubes 559 will be mounted to the medial portion of the shuttle and piston rod assembly in the same manner, for example, as hitherto described in connection with tube 131 in FIGURE 1. Other types of mountings of the inner extremities of the respective oil feed (or return) tubes may also take the form shown in FIGURE 17 and also FIGURE 7. In FIGURE 33 the outer extremities of the respective tubes 559 are threaded at area 560 to receive respective conical nut 554. An annular channel 561 is disposed between piston rod 541 and tube 559 and communicates with an enlarged annular channel 562 which is the space generally defined by tube 559 and externally circumscribing piston rod 541. Hence, provision is made in the structure in FIGURE 33 so that coolant will proceed upwardly through annular channel 562, thence through channel 561 to communicate with the underside of coolant control plate 556. Subsequently, coolant will flow through the apertures 558 and 558' of plate 556 so as to proceed to the upper surface thereof and from thence flow downwardly through the tube 559. Disposed within each cylinder 504 (see FIGURE 32) will be a piston displacement gland 562 which in part is spaced from the cylinder wall so as to permit the travel therebetween of piston-half 548. A partition plate 563 is secured by bolts 564 to respective bearing housing 509 to retain conventional oil wiping ring assembly 567 against carrier bearing plate 568. Carrier bearing 569 is a conventional ball and socket, self-aligning bearing which is shouldered at 570 against housing 509. The ball 571 is advantageously provided with inner annular groove 572 and with radial passageways 573 for permitting the conduction of oil therethrough to the bearing surface at the bore 574 of ball 571 and piston rod 541. In a similar manner a groove 575 may be supplied the interior of bearing housing 509 for accommodating ball and socket lubrication of this self-aligning carrier bearing.

Leads X, Y, Z from each of the three-phase generators 517 and 518 are coupled through conduits 576, 577 to junction means 692, such as a transformer, and output leads U, V, W therefrom will be available to provide electrical power, derived from the two generators, to supply a given load. Leads F, G and H, I branch off from generator leads Y, Z and connect to the core windings 578A and 578B (schematically indicated) of differential relay 578. The windings 578A and 578B are so constructed as to render pole 693 in a central position between contacts M, N when nominally equivalent electrical energy is sup-

plied 578A, 578B from generators 517 and 518 in balanced condition. When the outputs of these generators are in imbalance, at or greater than a predetermined degree, then pole 693 will contact either M or N, depending upon which generator output is greater, and in either event a secondary circuit including power supply PS and leads L, L', LA and LA', connected as shown, will be closed through the differential relay contacts. This energizes solenoid valve V which shuts off fluid input through conduit 505 to cylinder 504, thus effecting a safety precaution for the structure where, for some reason, generator output imbalance has occurred.

Likewise, normally open pressure switch NOPS, disposed in the output circuit of pump 525 which is driven by motor 691, is shunted across the series connected power supply PS and solenoid valve V and is so constructed, in conventional design, that a predetermined pressure drop in the lubricant pumping output circuit (524) will, through the closing of NOPS, shut off input to 505 via normally closed solenoid valve energization of valve V. Motor 691 should be powered by an independent circuit.

Piston 579 is illustrated in FIGURE 35, the same being shown to comprise piston halves 547 and 548 as hereinbefore explained. Shown in FIGURE 35 are pluralities of piston apertures 549, 550, 551, and 552. The piston aperture series 550 and 552 will be diametrically opposed to those at 549 and 551, respectively, so that a balanced condition with respect to pressures within the piston will be balanced so as to render negligible side thrust wear of piston and cylinder which would otherwise be present due to undirectional, pressure side-thrust in the piston skirt. In FIGURE 35, if the aperture series 549 are input apertures, then the aperture series 550 will be exhaust apertures. Correspondingly, if the aperture series 551 is an exhaust series, then aperture series 552 will be a pressure input series of apertures. The reverse situation, of course, will obviously hold true. In the present embodiment, it will be noted that there are series (really two series) of piston apertures in the upper and lower portions of the piston 579, and, further, there is present at the upper and lower portions of each respective cylinder 504 a respective pressure input port as at 506 and exhaust port as at 505.

It is understood that the cylinders 504 on both sides of the structure are identical. Let the cylinder at the top of the drawing be considered in connection with piston 579 in FIGURE 35. Pressure input port 506 and exhaust port 505 will be respectively operative, for example, with aperture series 549 and aperture series 550. Aperture series 549 of piston 579 will hereinafter be shown with reference to the porting diagrams to be explained; the piston input apertures 549 will come in sequential registry with pressure input cylinder port 506 during a nominal 180° travel of the piston. During upstroke the fluid received by this half of the piston will be exhausted through piston aperture series 550 and sequentially through exhaust cylinder port 505. Correspondingly, piston aperture exhaust series 551 will come in sequential registry with pressure input port 508, see FIGURE 34, during the upstroke of representative piston 579. The fluid is exhausted from beneath partition 545 through cylinder exhaust port 508 as piston apertures 551, shown in piston 579 in FIGURE 35, come in sequential registry therewith.

It will be noted in FIGURE 32 that there is a long isolation area between the interior of housing 510 and the displacement area of piston 579. This is to insure that, if the engine portion of the structure is being driven by steam, or water, or other media, the same will be totally precluded from entering into the lubricating chamber within housing 510.

As to the cylinder construction, the cylinder head 580 is secured by attachments 581 to cylinder 504 and completes the cylinder construction. The depending portion 582 of cylinder head 580 forms a travel path 583 between

itself and the piston 579 to accommodate the travel therethrough of piston half 547. Corresponding travel path 584 is disposed between piston displacement gland 562 and cylinder 504 to accommodate the travel therethrough of lower piston half 548. Carrier bearings as at 569 will be disposed on both sides of shuttle 118 relative to piston rod 541. As will be noted, ample lubrication is supplied the respective carrier bearing ball 571 owing to its proximity to housing 510. Drain-back passage is supplied at 585 to permit oil wiped from the piston rod 541 by wiper rings 567 to drain back into the housing 510.

In FIGURE 36 is illustrated a generator pair driven by a combustion-driven piston 611 scavaged by a pumping cylinder 635. Other types of driving means as heretofore explained in the invention may be employed to drive a pair of generators such as those illustrated in FIGURE 32. Merely by way of example, FIGURE 36 depicts opposed pistons, one of a combustion cylinder and the other of a pumping cylinder, which are so related structurally that the pumping action of air compressor piston 339 scavenges exhaust gasses from the firing cylinder during a portion of the back-stroke of the latter. Generators 517 and 518 are mounted on support stand 516 in a manner hitherto described in connection with FIGURE 32. Cone 521 and inner bearing plate 588 are interconnected together by attachments 600 to housing 589. Bearing plate 588 is substantially identical to bearing plate 523 in FIGURE 32, excepting that this time the bearing plate includes lubricating passageway 601 which communicates directly with passageway 602 of its respective rotor. Counter-weight 603 is bolted to rotor member 604 of rotor 16 by attachments 605. Plug 606 is threaded into passageway 602 so as to direct lubricant through passageway 607 to bearing socket 186. The oil passageways of the bearing socket and bearing 188 are as described previously in connection with FIGURES 7 and 10. Shuttle 251 is provided with medial portion 278 and mounts the balls 188 in a manner hitherto explained in connection with the embodiment shown in FIGURES 7 and 10. Lubricant pump 608 is shown in block form only, is connected by conduit 609 to passageway 601, supplying a pressure feed of lubricant through the rotor and sockets 186, through balls 188 and shuttle 251 to the piston rod 610. The circulation is as described previously. A piston 339 is secured to piston rod 610 in a manner described in connection with the former and piston rod 250. As to the interconnection of piston rod 610 and piston 625, the same is illustrated in FIGURE 37. Substitute tube 612 is shown to be mounted as by threads at 613 to conical retainer nut 614. Nut 614 is provided with suitable side recesses 615 to provide oil passageways 616 and 617 communicating with the annular region 618 between tube 612 and piston rod 610 and area 619. A washer-type coolant flow constrainer plate 620 is secured to tube 612 by locking nut 614; thus, oil or other lubricating coolant will flow outwardly through tube 612 (and through its companion tube 613 at the opposite end of the piston rod) to proceed to the end thereof and flow back between these tubes and the piston rod 610. With respect to FIGURE 37, the lubricating coolant will proceed in a direction C outwardly into area 621 and from thence will fan out radially to enter areas 619 and subsequently proceed to passageways 617 and 616, and through annular region 618 to be directed to proceed outwardly into the piston interior area through pop-off valve 622. Aperture 623 is simply a metering hole for regulating flow. It is important to know that the lubricating system through the medial tubes as at 612 and underneath the piston crown renders oil or other coolant immediately available for spraying, as through pop-off valve 622 and orifice 623, directly underneath the piston crown and against the piston walls and the lower crown surface. This pressured oil cooling at this point is highly desirable for the purpose of conducting heat away from the piston area. Appropriate oil rings 624 will be used at 624 and compression rings at

623. The piston 625 discussed is a firing piston having both reciprocal and a sweeping motion within cylinder 626. Cylinder 626 will include plural cylinder exhaust ports 627 on one side of its inner periphery and plural scavenging air intake ports 628 and 628' on another portion of its inner circle. Apertures 628 and 628' are disposed in communication either by shroud or by other means with cylinder intake ports 629 and 630, and apertures 627 are disposed in communication with cylinder exhaust port 627' (indicated for convenience in dotted lines and leading to a conventional exhaust manifold, not shown). Plumbing 631 and 632 interconnect cylinder intake ports 629 and 630 to cylinder exhaust ports 633 and 634, respectively, of cylinder 635.

Cylinder 635 is simply a pumping cylinder and may be identical to that illustrated in FIGURE 17. The water jacket structure at 636 with its associated conduits and connections is substantially identical to that illustrated in FIGURE 17. Slight modification has been made in the cylinder head in FIGURE 36 relative to FIGURE 17, in that cylinder head 587 is supplied with a central chamber 637, and water or other coolant is pumped therethrough by conduit 638 and 639. Appropriate cooling fins 640 and unions 641 will be supplied by the plumbing 631 and 632 as needed.

Water jacket structure 642 is preferably disposed over the firing cylinder head 643 which is configurated in the manner indicated in FIGURE 36, and the same includes circulation constraining plate 647 which is coaxially disposed about the central portion 648 of cylinder head 643 and which is retained in place by spacers 649, 650 and one or more bolts 651. Suitable O-rings as at 652 provide a seal between the coolant jacket 642 and the general cylinder construction. Coolant conduit 653, 654, and 655 are connected thereto for accommodating the circulation of water or other coolant through the cylinder heads and across the walls thereof to appropriate outlet conduit.

The upper part of FIGURE 36 indicates that suitable conduit stubs 657 and 658 may accommodate connection to exhaust ports 633 and 634. Configurated washer 659 and locking nut 660 will be supplied all the connections requiring the same. Chambers 661 and 662 offer communication between cylinder intake ports 663 and 664 into the cylinder intake ports generally indicated at 656, and from thence into the piston area as before explained in connection with FIGURE 17.

Accordingly, during the upstroke (compression stroke) of the pumping cylinder 635, air is compressed above medial partition 664. This occurs at a time when firing piston 625 is proceeding away from the head of firing cylinder 626. The port relationships of pumping cylinder 635 and the ports of firing cylinder 626 are such that at or just after cylinder exhaust ports 627 commence to open (i.e., by the drop of piston 625 commencing to pass over the same), the piston apertures and cylinder ports associated with exhaust in connection with the pumping piston 339 will come into registry so as to supply jets of forced air through the firing chamber, i.e., within cylinder 626 so as to aid in exhausting combustion gases from within the interior of cylinder 626 and out exhaust ports 627 communicating with 627'. It is to be noted that the exhaust ports 627 will be disposed on one area of the cylinder wall with reference to cylinder 626, whereas the scavenging air intake ports 628 and 628' will be disposed on remaining portion of the cylinder's circle near the lower portion of the stroke. One type of air compressor porting specifically contemplated will be illustrated hereinafter in the porting charts which will be discussed.

For diesel-type operation, there will be included a cam 665, secured by set screw 666 to generator shaft 667, which cam will actuate what is known as a fuel injector 668. This injector will be coupled to an appropriate fuel supply 669 so as to feed cam-synchronized surges of fuel through plug 670 into the firing chamber of cylinder 626. But a

simple cam arrangement has been illustrated. There are in existence other types of sophisticated cam actuators of an alternate design to accommodate the timing desired.

In the structure of FIGURE 37 it will be noted that, for coupling of the piston rod 610 to piston 625 there may be included mounting lugs 671 which seat against annular shoulder 672 directly underneath the piston crown and which is secured to the flanged end 673 of piston rod 610.

FIGURE 38 indicates a representative diagram of the pumping cylinder port construction of FIGURE 36. The numeral 295 designates a permissible, single piston aperture at positions numbering 295 #1, 295 #2, 295 #3, 295 #4, 295 #5, 295 #8. Correspondingly, 656(A)-656(E) indicate cylinder ports which are in stationary positions. There is also shown a cylinder port 674 which serves as an exhaust port, the previous ports 656(A) to 656(E) being intake ports.

FIGURE 38 is in fragmentary view and illustrates a diagrammatic presentation of a 180° roll-out of a representative one-half of piston 339 of FIGURE 36 superimposed over the porting arrangement of a representative side of the cylinder 635. These cylinder ports and piston apertures are so arranged in construction that the piston aperture 295 will proceed from position #1 through position #8 and subsequently over a cylinder exhaust port 674 to exhaust compressed air, for example, through conduits 631 and 632 into cylinder 626 of FIGURE 36 for the scavenging operation hitherto explained. It is to be noted that the construction of the shuttle 251 and the position of the bearing balls 188 and the socket structure associated therewith and the angulation of the latter with respect to their rotors will determine the width of the sweep circle at C in FIGURE 38. All of these factors must be taken into account, therefore, in order to properly position the series of cylinder ports 656A-656E and exhaust port 674 in any particular construction.

FIGURE 38 has been shown and described to illustrate a simplified porting diagram for one type of piston and cylinder construction which may be utilized in the FIGURE 36 embodiment of the invention. Frequently it is desired to incorporate quite large piston and cylinder constructions for supplying large volumes of air or other compressibles under pressure. Further, and most important for large piston and cylinder constructions porting, as indicated in FIGURES 39 and 40, is ideally suited for multi-stage work where, by virtue of the inclusion of exhaust lead apertures in the piston, the piston and cylinder combinations may be built to exhaust air or other media at a particular needed pressure and will not be obliged to produce higher pressures in order to permit the compressed media to escape from conventionally used reed valves or plate valves, all of which need not be employed in the present invention. Thus, the carbon sleeve or oil ring seals hereinbefore explained and/or the travel path distance relating to cylinder ports and piston apertures during certain portions of the stroke insure a completely adequate seal between the piston and cylinder, particularly at high speeds, such that conventional valving means is not required.

There are several considerations which are important at this juncture. In the first place, the prime consideration with reference to FIGURES 39-44 is to provide a pumping cylinder and piston combination wherein volume output is large. Secondly, there must be a minimum of unexpelled volume and, finally, a minimum of restriction on the outflow of compressed media within a cylinder during the exhaust portion of the cycle, and this in a manner such that pressures within the cylinder need not be made to be greater than the final output pressure desired. For example, let it be assumed that a multiple-stage compressor is under consideration. We shall consider a simple two-stage compressor incorporating the piston and cylinder construction of FIGURES 39 and 40. See also FIGURES 17, 21 and 36 in which the piston and cylinder of

FIGURES 39 and 40 may be incorporated as the respective pistons and cylinders of these figures. As an example, such incorporation in FIGURE 21 will now be discussed.

5 Assume that the cylinder of FIGURES 40-44 constitutes cylinder 296 in FIGURE 21 and that a similar cylinder is disposed at 296'. It will be noted in passing that compressed air, for example, in cylinder 296 when made in accordance with the teaching of FIGURES 40-44, will 10 pump air through conduit 347-350 to cylinder 296', and that the air is cooled in transit by the fins of the conduit shown. It is to be noted that the compressed air is simply "dumped" into the next stage without undergoing constriction such as reed or plate valves; further, the cylinder designs can be chosen such that the output pressure of the first stage at cylinder 296 very nearly equals the pressure which will be experienced at cylinder 296' on the intake.

In FIGURE 39 the piston 683 is shown to include 20 groups I, II, III, and IV of apertures 295 and 295'. Groups I and II can be seen directly. Groups III and IV are on the rear side of the piston shown. FIGURE 40 is a 360° roll-out of a cylinder 684 which will be utilized with the piston 683 in FIGURE 39. FIGURE 40 illustrates that the cylinder 684 will include plural port groups 25 675, 677, 679, and 681 of intake ports 675A to 685D, and respective exhaust ports 676, 678, 680, and 682, respectively. Line 685 represents a locus of points defining the movement of the leading corners of apertures 295 and 295' of group I apertures in FIGURE 39. Correspondingly, arcuate line 686 defines the locus of points of movement of the leading corners of apertures 295 and 295' of group II in FIGURE 39, and so on. Thus, it is to be noted that each group, I, II, III, IV of apertures 295, 30 295' in FIGURE 39, travels in an arcuate path which is respectively related to a particular group (675, 677, 679 and 681) of cylinder intake ports and respective exhaust ports, 676, 678, 680, and 682.

FIGURES 41-44 illustrate the relative relationships between the cylinder ports of FIGURE 40 and piston apertures in FIGURE 39 at four locations of piston stroke, namely, at 12 o'clock, 9 o'clock, 6 o'clock and 3 o'clock positions relative to FIGURES 41-44, respectively. In these four figures (FIGURES 41-44) a study of the functional relationships can be readily observed when it is understood that roll-outs of the piston and cylinder have been made, with the piston being superimposed over the cylinder so that the cylinder ports are in dotted line configuration whereas the piston apertures are in solid line configuration. It will be noted that by virtue of the angular relationship of pairs of apertures 295 and 295', in their respective pairs, that increased intake is facilitated during the bottom-half of the intake portion of the stroke, see FIGURE 43, and, further, exhaust is facilitated by 55 mutual registry of apertures 295 and 295' with respect to exhaust ports 676, 678, 680 and 682 of cylinder 684. Thus, large intake and large exhaust is possible by virtue of the port and aperture construction of the cylinder and piston in FIGURES 40 and 39. Note that this can be 60 obtained by the use of pluralities of individual apertures and ports of restricted size so that holding shape of the cylinder wall during fabrication is not interfered with, and especially so that wall strength is preserved and possible wall distortion minimized.

65 It will be noted that each group (I, II, III, IV) of apertures 295 and 295' sweep past their respective series of cylinder intake ports (675, 677, 679, 681) and subsequently across their respective exhaust ports (676, 678, 680, 682) so as to complete the 360° function of the 70 pumping cylinder.

At first thought, it might appear that the connection of external conduit to the porting apertures and ports would be very expensive. A brief reference to FIGURES 30 and 17, however, reveals that this is not the case. And,

indeed, expensive conduit connection to cylinders incorporating multiple ports as disclosed is not great. This is due to the fact that simply four mounting pads as a maximum will be needed to accommodate cylinder 684 in FIGURE 40, whatever its size. This is indicated in FIGURE 25, for example, wherein a series of cylinder ports is accommodated by a single mounting pad at 378. Further, it is conceivable, and, as is shown in FIGURE 17, that a single circular jacket member might be employed and have appropriate mounting bosses as at 302 and 303 to accommodate intake air or other media. Furthermore, the conduit as at 308 and 309 might be eliminated and simply a screen be disposed over this intake area of the cylinder 296, so that ample intake air might be screened for each of the groups of cylinder ports, 675, 677, 679, and 681. The exhaust apertures, 676, 678, 680, and 682, may be accommodated by simple threaded piping or otherwise, as desired. Thus, it is noted that there is virtually no restriction for intake air into the cylinder 684. Exhaust conduit will of course be reduced in size owing to the high pressure of such exhaust.

In connection with FIGURES 39-44, a brief rereference to FIGURE 21 may be helpful to appreciate the advance to the art given by the present invention in a special particular. FIGURE 21 illustrates an air-cooled two-stage compressor. The particular porting design shown takes advantage of the pressure of any unexpelled volume within the cylinder to initiate the down-stroke return of the piston, and, in addition, insures good sealing. With respect to the latter, it is to be noted that the path between exhaust port 676 and the first intake port 675A, for example, is made as elongated as possible so that there is little or no chance of air short-circuiting through the sealed piston and cylinder surfaces.

FIGURES 45-48 are diagrammatic presentations of a representative piston rolled out over a representative cylinder which may be used in the construction of FIGURES 24 and 29. Cylinder ports are shown in dotted line squares. Piston apertures are indicated in solid line squares. While square or other rectangularly shaped holes and ports are desired for sharp cut-off in opening in some applications, it will be understood that round apertures and ports or some of other configurations will be permissible in some cases. Cylinder port series 380 in FIGURE 25 is illustrated in FIGURE 45 as compression cylinder ports 381A to 381G. A similar set of cylinder port means 380 is likewise illustrated on the right-hand side of FIGURE 45. There is also illustrated in FIGURE 45 the cylinder exhaust ports 383 and 384. The porting configuration of FIGURES 45-48 is suitable for compressor design employing double-acting piston means, and will accommodate compressible media such as air or steam. FIGURES 49-52 illustrate porting for non-compressibles such as hydraulic fluid, oil, or water, where it must be appreciated that there should be an almost immediate intake of the liquid employed after the cylinder exhaust port 384 comes out of registry with piston aperture 396. In other words, and more broadly, there must exist a passageway through the cylinder for every displacement caused by the movement of the piston. A great advantage is present and should be preserved, in the case of pumping compressibles such as air in providing dead space between exhaust port 384 and the first intake port 381A.

In FIGURE 45, the top dead center position of the piston relative to the cylinder is shown and is indicated by the arrow on the piston trace ellipse. Piston 375 is also shown in FIGURE 29 and may, for example, be employed in FIGURE 1 to constitute a pumping cylinder thereof. Piston aperture 396 is just coming out of registry with cylinder exhaust port 384. During the continuation of piston stroke to 9 o'clock position (FIGURE 46), it will be noted that the piston intake and exhaust aperture 398 is totally out of registry with the series of cylinder ports 381. During this time, however, the piston intake and

exhaust aperture 396 will proceed downwardly and sweep over cylinder intake ports 381A, 381C, 381D, and 381E of the port series 380. At bottom dead center position in FIGURE 47, the piston aperture 396 is just coming out of registry with cylinder intake port 381E. At this time piston aperture 398 comes out of registry with cylinder port 383 and proceeds upwardly in progressive registration over cylinder ports 381F, 381G, 381D, and 381C, during the intake portion of the stroke. This is also illustrated in FIGURE 48. During this interval the aperture 396 of the piston is disposed out of registry with all of the cylinder ports. Accordingly, it is to be noted that one selected grouping from among the series of cylinder ports designated 380 will be employed during the intake portion of the stroke for the upper piston-half, whereas others of the same series are employed by the lower piston-half during its intake portion of the stroke. Thus, it is readily perceived how the piston and cylinder porting may employ identical ports for intake by both sides of the double-acting piston, and this cooperating with the sweeping action of the piston 389 within the cylinder 375. Thus, it is noted that what is present is a full and complete intake of air occurring throughout a possible 180° of piston travel for each piston-half. On the compression stroke the air or other medium is compressed to the pressure which is to be used, and, by virtue of the elimination of reed and plate halves in the design and the unrestricted dumping of the compressed air at exhaust position, this does not necessitate an increase in pressure of the medium employed above that which is desired at the exhaust point as usable pressure.

The advantages of the port groupings illustrated in FIGURES 45-48 are many, among which are included the following:

- 35 (1) Where groupings of ports are such as in FIGURES 45-48, they can serve a double purpose, i.e., promote intake on both sides of a double-acting piston thus reduce the number of holes required for a given volume requirement;
- 40 (2) The number of ports for a given volume requirement is reduced, while strength of the cylinder is enhanced;
- 45 (3) Since the necessary ports can be grouped to serve double purposes, this will allow larger uninterrupted surfaces in the cylinder wall from which the inter-port seal is obtained as before mentioned.

FIGURES 49-52 relate to the pumping cylinder 504 in FIGURE 32 and, in general, relates to porting configurations suitable for liquid pumps and fluid (e.g., liquid, steam or air) motors or non-compressibles. With reference to FIGURES 32 and 49-52, it will be noted that the piston 579 is supplied with four groupings of apertures 550 and 551, which are respective exhaust aperture groupings, and 549 and 552 which are respective input groupings. The groupings 550 and 549 and also the groupings 551 and 552 are respectively disposed in general orientation 180° apart and, when the four groupings are considered together, it will be noted with reference to FIGURE 49 that, while not so required, the approximate spacing between groupings may be roughly 90°. This can be varied for varying conditions. Of importance, however, is the spacing between cylinder exhaust port 505 and cylinder input port 506. Correspondingly, there must be noted the cylinder input port 508 and its spacing from cylinder exhaust port 507. Reference may also be had to FIGURE 34 in connection with this spacing requirement. The purpose for the relatively close spacing of these two pairs of ports, less than 90° as shown, is so that upon the upsweep of piston aperture grouping 550 past exhaust port 505, the cylinder input port 506 will be in line to receive the sweeping thereacross of input aperture group 549. The same reasoning will apply to cylinder input port 503 and cylinder exhaust port 507 and the corresponding piston aperture groupings 551 and 552, respectively. The disposition of the four groupings of piston apertures with the respective cylinder ports are

illustrated in FIGURES 49, 50, 51, and 52 at 12 o'clock, 9 o'clock, 6 o'clock, and 3 o'clock positions. It will be noted with reference to FIGURES 32, 34, and 49-52 that the arcuate sweeping character of the piston within its respective cylinder is accommodated for by plural groupings of multiple piston apertures at 549-552. With this, however, is the presence of but four cylinder ports, two intake and two exhaust, to accommodate this multiplicity of piston apertures. Thus, there will be but one cylinder input port and one cylinder exhaust port for each half of the double-acting piston 579 and these may be supplied screw-in connections to their respective conduit. Hence manifold techniques necessary can be accomplished by the simplest possible mechanical means.

FIGURE 53 indicates a "short" piston construction of single-acting character. FIGURE 54 is a simplified, roll-out view of a cylinder 692 which is designed to cooperate with the piston 691 of FIGURE 53. The design of the piston and cylinder in FIGURES 53 and 54 permits a piston-cylinder construction of reduced over-all length across the cylinder assembly. For convenience of illustration, the piston in FIGURE 53 is shown in enlarged scale relative to the scale of the cylinder in FIGURE 54. A substantially accurate indication as to scale is indicated in FIGURES 55-58. The precise reason for the accomplishment of shortness in length of piston-cylinder design is that, since the piston in this embodiment is not double acting, it need only be as long as one-half of the piston shown in FIGURE 35, for example. In comparing the FIGURE 53 piston embodiment with that shown in FIGURES 22 and 23, it will be noted that not only is the intake series of piston apertures 687A present in FIGURE 53, but also the exhaust aperture, formerly at the opposite piston half, is now disposed at 688A in FIGURE 53. Thus, only one side of the effective "medial" petition need be used to complete the piston construction. Groove 693 is provided in the piston construction of FIGURE 53 to accommodate the insertion therein of a conventional oil-wiping ring. The piston in being single-acting can simply be designed within the cylinder to be disposed immediately adjacent the central housing of the machine so as to be proximate a turbulent, lubricating oil area of the housing, such as housing 510. In such an event, then, such turbulence as may be present in the housing will amply lubricate the cylinder wall during the piston's compression stroke and, during the down-stroke the oil wiping ring will simply scrape excess oil from the cylinder wall and back into the housing in a conventional manner. A particular point to note is that any ring disposed in groove 693 does not have to pass over any cylinder ports. Additionally, owing to inter-port seal relative to the piston, no compression rings will be needed.

Piston intake aperture group 687A and piston exhaust aperture 688A are illustrated in FIGURE 53. It will be understood that for a balanced condition it is essential that there exist corresponding groups of apertures 687B and 688B, respectively, on the opposite side of the piston, see FIGURES 55-58. In such event, then, the cylinder will have four ports 689A, 689B, 690A, and 690B. Cylinder port 689A and 689B are cylinder intake ports accommodating piston aperture series 687A and 687B, respectively. Correspondingly, cylinder exhaust ports 690A and 690B accommodate, as to registry, the piston exhaust apertures 688A and 688B, respectively. The relationship between the piston aperture group 687A and 687B and of piston aperture 688A and 688B with respect to cylinder ports 689A, 689B, 690A and 690B, are illustrated in FIGURES 55-58 for 12 o'clock, 9 o'clock, 6 o'clock, and 3 o'clock piston displacement positions. As the piston proceeds in down-stroke from 12 o'clock position the piston intake aperture series 687B sequentially passes over cylinder intake port 689B as illustrated in FIGURE 56. There will be a corresponding passage of piston intake aperture series 687A over cylinder intake port 689B as illustrated in FIGURE 56. There will be

a corresponding passage of the piston intake aperture series 687A over cylinder intake port 689A. Bottom dead center position is illustrated in FIGURE 57, and the piston intake series 687A and 687B will progress to leave registry with cylinder intake ports 689A and 689B. The piston compression stroke is illustrated in FIGURE 58 wherein all of the piston apertures and cylinder ports will be out of registry until 12 o'clock position is reached or is about to be reached, at which time piston exhaust apertures 688A and 688B and respective cylinder exhaust ports 690A and 690B come out of registry to complete the exhaust function prior to a new intake. Thus, what is had in the embodiment illustrated in FIGURES 53-58 is a single-acting piston-cylinder combination having a simplified porting system which can accommodate compressors of reduced, lengthwise dimension over the cylinder assembly.

By way of general observation, it will be seen from the present case that the invention is uniquely designed to accommodate plural components in a preferred, balanced design. These components may take the form of plural generators coupled to output balanced lanes of the volume displacement means, to plural motors as components supplying mechanical energy to a compressor type unit or pumping unit, and, indeed, to dual or plural pumping, compression, vacuum, and other cylinder means for accomplishing any one of a number of desired pumping, compression, firing, firing and scavenging, and other functions.

A number of different types of porting arrangements have been illustrated, and the manner of construction of the various cylinders and their pistons have been shown for the accomplishing of single-acting and double-acting cylinder functions. It will become apparent that there are many other types of porting arrangements which might conceivably be devised for various uses not specifically delineated herein. Further, single ports may be constituted by plural ports, single apertures by plural apertures, and multiplicities of apertures and ports may conceivably in some instances be reduced to single openings, as desired. However, it is believed that the porting arrangements hitherto discussed in detail have illustrated most types of porting which are to be desired in practicing this art. However, various variations may be made in porting in cylinder construction to accommodate a particular type of engine, motor, motor-generator, compressor, fluid pump and so forth, as may be under consideration. Whatever design is specifically used, however, it will be noted that by virtue of the motion transforming mechanism employed to accomplish the reciprocation and simultaneous cyclical revolvement of the piston or pistons within their respective cylinders, there is insured substantially vibration-free operation of the equipment, and particularly by the addition of appropriate counter-weights or appropriate rotor design in general of the rotors, and this is a feature not lightly to be considered in view of the very objectional vibrations which are present in conventional equipment such as compressors, for example.

Many of the principles, combinations, and subcombinations herein disclosed, while particularly adapted for favorable employment in the volume displacement means of the present invention, will be useable in other contexts such as in the motion transformer (converting reciprocating motion to rotary motion) art and in the engine, reciprocator, power drive, power conversion, power coupling, shaker, lubrication, cooling and other arts by way of example.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. Piston-ported volume displacement means accommodating multiple, work effecting components including, in combination, a piston rod journaled for rectilinear reciprocation and oscillation about its own axis; piston means affixed to at least one extremity of said piston rod and having piston aperture means; shuttle means affixed to said piston rod for keying said piston rod to said shuttle means for translation along and revolvement about the axis of said piston rod in accordance with the motion of said shuttle means with respect thereto, said shuttle means being nominally disposed in right angle relationship with said piston rod and having a pair of rectilinear, oppositely extending arms; a pair of spaced rotor means disposed nominally equidistantly on opposite sides of said piston rod in the region of said shuttle means, said rotor means having a common axis of rotation which nominally passes through the juncture of said piston rod and said shuttle means at piston mid-stroke position; means journaling said rotor means for enabling the mutual, opposite revolvement thereof at nominally equal angular velocities; means respectively coupled to said rotor means, respectively, for revolving in correspondence with said rotor means in respective, opposite directions at nominally equivalent angular velocities, to move in respective revolvements in correspondence with the movement of said piston rod; respective means, articulatedly connecting the respective shuttle arms, nominally equally eccentrically, to respective ones of said rotor means, and said respective means, said rotor means, and said shuttle means being so constructed and arranged that the disposition and motion of said shuttle means throughout its travel is nominally in a reciprocating, right-angle, transverse plane with respect to said piston rod and also that said piston rod and said piston means coupled thereto reciprocate along and simultaneously, cyclically revolve in oscillatory movement about the axis of said piston rod; cylinder means circumscribing said piston means in operative relationship with respect thereto and having intake and exhaust ports so arranged as to register with said aperture means of said piston means at desired points in the reciprocal oscillatory path of travel thereof to enable passage of fluid material therethrough, through said cylinder means and piston means, and thereby effect desired work.

2. Structure according to claim 1 wherein said volume displacement means includes a pair of electrical generators comprising said components and including individual rotors, said generator rotors individually constituting at least in part said means respectively coupled to said rotors, respectively, said piston means and cylinder means constituting, at least in part, fluid motor means for supplying power to said piston rod, the said piston aperture means and cylinder ports of said piston means and cylinder means, respectively, being so positioned in construction and arrangement with respect to each other to respond to the reciprocal and oscillatory movement of said piston means within said cylinder means to effect fluid input, through selected ones of said cylinder intake ports and said piston aperture means into said cylinder means during the said piston means' power stroke and, subsequently, to effect fluid exhaust from said cylinder means back through said piston aperture means and a said cylinder exhaust port during the said piston means' return stroke.

3. Structure according to claim 1 wherein said volume displacement means constitutes at least in part a fluid-driven motor, said piston means comprising a pair of piston means respectively connected to opposite extremities of said piston rod and said cylinder means comprises a pair of cylinder means individually and operatively encasing said individual piston means, respectively, the combination of the said cylinder means with respective ones of said piston means constituting said components, the said piston aperture means and cylinder ports of each piston cylinder means combination being so positioned in construction and arrangement with respect to

each other to respond to the reciprocal and oscillatory movements of said piston means within said cylinder means to effect fluid input, through selected ones of said cylinder ports and said piston aperture means, into said cylinder means during the respective piston means' power stroke and, subsequently, to effect fluid exhaust from said cylinder means back through said piston aperture means and as said cylinder port of the respective piston-cylinder means combination during the respective piston means' return stroke.

4. Structure according to claim 1 wherein said volume displacement means constitutes a fluid pump including, as said means respectively coupled to said rotor means, a pair of motors constituting said components, said motors being respectively coupled to said rotor means for driving the same, said piston aperture means and cylinder ports being so positioned in construction and arrangement with respect to each other to respond to the reciprocal and oscillatory movements of said piston means within said cylinder means to effect fluid intake, through said piston aperture means and at least one of said cylinder ports when registered, of said cylinder means and piston means, to within said piston means during the piston intake stroke and, subsequently, to effect pressurized fluid exhaust through said piston aperture means and at least one other of said cylinder ports, during return piston stroke, to effect a pressurized output of said fluid material.

5. Structure according to claim 1 wherein said cylinder means includes a lubricant sleeve provided with ports registering with said cylinder ports, bearing upon said piston means, and contacting the latter throughout its travel within said cylinder means.

6. Structure according to claim 1 wherein said piston is provided with a plurality of longitudinally and radially spaced apertures in a central area thereof, said cylinder means is provided with a plurality of intake and exhaust ports about a central area thereof, said cylinder means includes at least one inner annular groove adapted to receive an oil feed and disposed in circumscribing proximity with said piston means and at a cylinder means wall area which, during piston means travel, is unswept by any of said piston aperture means; and wherein said volume displacement means includes means for delivering an oil feed under pressure to said inner annular groove for supplying a lubricating seal between said cylinder means and piston means.

7. Structure according to claim 1 wherein said volume displacement means constitutes a prime mover and wherein said piston means is affixed to one extremity of said piston rod and constitutes an air compressor piston, and wherein said volume displacement means includes a combustion-driven piston affixed to the remaining extremity of said piston rod and a combustion cylinder operatively containing said combustion-driven piston, said combustion cylinder including scavenging air intake aperture means and exhaust aperture means, conduit interconnecting at least a cylinder exhaust port to said scavenging air intake means, and said piston means and cylinder means, and said combustion cylinder and combustion-driven piston being so constructed and arranged with respect to port timing as to effect a passage of compressed air from said cylinder means to said combustion cylinder at the latter's exhaust period.

8. Structure according to claim 1 constituting a plural-stage air-compressor, wherein said piston means comprise a pair of pistons secured to opposite ends of said piston rod, said cylinder means comprising a pair of cylinders respectively operatively disposed about said pistons, and wherein said volume displacement means is provided with conduit interconnecting a said cylinder exhaust port of one of said cylinders with a said intake port of the remaining cylinder, said pistons and cylinders being so constructed and arranged that exhaust of one of said cylinders is timed with the intake of the re-

maining cylinder with which it is interconnected by said conduit.

9. Structure according to claim 1 wherein said volume displacement means constitutes at least in part a fluid-driven motor, said piston means and said cylinder means comprising a single piston and a single cylinder, respectively, the latter operatively encasing the former, said piston aperture means and said cylinder ports being so positioned in construction and arrangement with respect to each other to respond to the reciprocal and oscillatory movements of said piston within said cylinder to effect fluid input, through at least a selected one of said cylinder ports and said piston aperture means, into said cylinder during the piston's power stroke and, subsequently, to effect fluid exhaust from said cylinder back through said piston aperture means and another of said cylinder ports of said piston and cylinder, respectively, during the said piston's return stroke.

10. A structure according to claim 1 wherein said volume displacement means constitutes a fluid pump, said fluid pump including power means comprising a pair of nominally matched, torque producing power means respectively coupled to said rotor means to rotate the latter in mutually opposite directions and at nominally equal angular velocities.

11. A structure according to claim 1 wherein said volume displacement means constitutes a fluid pump, said fluid pump including power means comprising a single, torque producing power means, and gearing means coupled to said power means for driving said rotor means to rotate the latter in mutually opposite directions and at nominally equal angular velocities.

12. Structure according to claim 1 wherein said volume displacement means includes a resilient bushing disposed between said piston rod and said shuttle means, supplying a resilient connection therebetween, and mounting means comprising structure mounting said shuttle means to said piston rod in a universal connection spaced from the center of said bushing.

13. Structure according to claim 1 wherein said shuttle means includes a resilient bushing disposed between said piston rod and said shuttle means, supplying a resilient connection therebetween, and wherein said volume displacement means includes mounting means comprising structure mounting said shuttle means to said piston rod in a universal connection spaced from the center of said bushing.

14. Structure according to claim 1 wherein said cylinder means and piston means comprise a pair of cylinders and a pair of pistons respectively disposed in said cylinders and affixed to opposite ends of said piston rod, and wherein said volume displacement means includes a lubricant containing housing mounted to and between said cylinders and encasing said rotor means and said shuttle means, stuffing gland baffle structure journaling said piston rod on opposite sides of said shuttle means and disposed proximate the junctures of said cylinders and said housing for isolating said pistons from said housing a source of cooling fluent, and means for circulating said cooling fluent through said stuffing gland baffle structure.

15. Structure according to claim 1 wherein said cylinder means and piston means comprise a pair of cylinders and a pair of pistons respectively disposed in said cylinders and affixed to opposite ends of said piston rod, and wherein said volume displacement means includes a lubricant containing housing mounted to and between said cylinders and encasing said rotor means and said shuttle means, stuffing gland baffle structure journaling said piston rod on opposite sides of said shuttle means and disposed proximate the juncture of said cylinders and said housing for isolating said pistons from said housing, and means for circulating the lubricant within said housing through said stuffing gland baffle means.

16. Structure according to claim 1 wherein said shuttle means is affixed to said piston rod in a universal connection.

17. Structure according to claim 2 wherein said volume displacement means includes control means, including relay means for stopping the supply of input power to said piston and cylinder means when said generators are in mutual imbalance, said relay means being electrically interposed between said generators and said control means being coupled to one said cylinder intake ports.

18. Structure according to claim 3 wherein, when liquid is to be employed as said fluid, said cylinder intake and exhaust ports and said piston aperture means are so constructed and arranged with respect to each other as to effect intake and exhaust in a continuous manner, both as to intake and exhaust strokes, respectively, and also as to continuity between intake and exhaust strokes, of said liquid through a said cylinder port and said piston aperture means into said cylinder means and through said aperture means and a said cylinder exhaust port out of said cylinder means.

19. Structure according to claim 4 wherein, when liquid is to be employed as said fluid material, said cylinder intake and exhaust ports and said piston aperture means are so constructed and arranged with respect to each other as to effect intake and exhaust in a continuous manner, both as to intake and exhaust strokes, respectively, and also as to continuity between intake and exhaust strokes, of said liquid through a said cylinder port and said piston aperture means into said cylinder means and through said aperture means and a said cylinder exhaust port out of said cylinder means.

20. Structure according to claim 4 wherein, when gaseous material is to be employed and said fluid pump constitutes a compressor, said piston aperture means and cylinder ports as so constructed and arranged with respect to each other to isolate each with respect to the other during a portion of the compression stroke of said piston means.

21. Structure according to claim 4 wherein, when gaseous material is to be employed and said fluid pump constitutes a compressor, said piston means comprises a double-acting piston having a medial partition and at least one wall aperture disposed on each side thereof constituting said piston aperture means, said cylinder means having a series of intake ports so constructed and arranged as to accommodating intake for said piston on both sides of said medial partition.

22. Structure according to claim 5 wherein said lubricant sleeve comprises a carbon sleeve.

23. Structure according to claim 17 wherein said relay means comprises a differential relay.

24. Structure according to claim 18 wherein said cylinder intake and exhaust ports and said piston aperture means are so constructed and arranged as to effect an overlap of intake and exhaust functions at both extremities thereof.

25. Structure according to claim 19 wherein said cylinder intake and exhaust ports and said piston aperture means are so constructed and arranged as to effect an overlap of intake and exhaust functions at both extremities thereof.

26. Structure according to claim 21 wherein at least some of said cylinder intake ports are so constructed and arranged as to constitute intake ports for said piston on both sides of said partition.

27. In a vacuum pump including a cylinder having porting ports longitudinally and radially spaced about a central region thereof, a piston operatively disposed in said cylinder and having porting aperture means longitudinally and radially spaced about a central portion thereof and means for reciprocating and oscillating said piston coupled thereto, an improvement comprising means for conducting oil under pressure to said cylinder, said cylinder having at least one annular groove disposed in com-

munication with said conducting means and about and always adjacent said piston at a cylinder area which is unswept by said piston's porting aperture means, and means for recovering oil from oil-entraining media expelled from said cylinder and for returning said oil to said conducting means.

28. A plural stage air-compressor including, in combination, first stage compression and second stage compression cylinders, a first and second pistons operatively disposed within said cylinders, respectively, a piston rod interposed between and affixed to said pistons, means for reciprocating said piston rod, said cylinders and pistons being provided with intake and exhaust port means and aperture means, respectively, for admitting and subsequently compressing air within said cylinders and expelling the same therefrom, and conduit means for connecting a said exhaust port of said first cylinder to a said intake port of said second cylinder, said ports and apertures of said pistons and cylinders being so constructed and arranged to time the exhaust of said first stage compression cylinder with the intake of said second stage compression cylinder.

29. Piston-ported volume displacement means accommodating multiple, work effecting components including, in combination, a piston rod journaled for rectilinear reciprocation and oscillation about its own axis; piston means affixed to at least one extremity of said piston rod and having piston aperture means; shuttle means affixed to said piston rod for keying said piston rod to said shuttle means for translation along and revolvment about the axis of said piston rod in accordance with the motion of said shuttle means with respect thereto, said shuttle means being nominally disposed in right angle relationship with said piston rod and having a pair of rectilinear, oppositely extending arms; a pair of spaced rotor means disposed nominally equidistantly on opposite sides of said piston rod in the region of said shuttle means, said rotor means having a common axis of rotation which nominally passes through the juncture of said piston rod and said shuttle means at piston midstroke position; means journaling said rotor means for enabling the mutual, opposite revolvment thereof at nominally equal angular velocities; means respectively coupled to said rotor means, respectively, for revolving in correspondence with said rotor means in respective, opposite directions at nominally equivalent angular velocities, to move in respective revolvments in correspondence with the movement of said piston rod; respective means, articulatedly connecting the respective shuttle arms, nominally equally eccentrically, to respective ones of said rotor means, and said respective means, said rotor means, and said shuttle means being so constructed and arranged that the disposition and motion of said shuttle means throughout its travel is nominally in a reciprocating, right-angle, transverse plane with respect to said piston rod and also that said piston rod and said piston means coupled thereto reciprocate along and simultaneously, cyclically revolve in oscillatory movement about the axis of said piston rod; cylinder means circumscribing said piston means in operative relationship with respect thereto and having intake and exhaust ports so arranged as to register with said aperture means of said piston means at desired times to enable passage of fluid material therethrough, through said cylinder means and piston means, and thereby effect desired work; a lubricating coolant containing housing encasing said rotor means and said shuttle means; and means for progressively circulating said lubricating coolant from said housing through said rotor means, said shuttle means, and into said piston rod at said universal connections and through said piston rod in a double-backed path, in progression, back to said housing.

30. Piston-ported volume displacement means accommodating multiple, work effecting components including, in combination, a piston rod journaled for rectilinear reciprocation and oscillation about its own axis; piston means affixed to at least one extremity of said piston rod and

having piston aperture means; shuttle means affixed to said piston rod for keying said piston rod to said shuttle means for translation along and revolvment about the axis of said piston rod in accordance with the motion of said shuttle means with respect thereto, said shuttle means being nominally disposed in right angle relationship with said piston rod and having a pair of rectilinear, oppositely extending arms; a pair of spaced rotor means disposed nominally equidistantly on opposite sides of said piston rod in the region of said shuttle means, said rotor means having a common axis of rotation which nominally passes through the juncture of said piston rod and said shuttle means at piston midstroke position; means journaling said rotor means for enabling the mutual, opposite revolvment thereof at nominally equal angular velocities; means respectively coupled to said rotor means, respectively, for revolving in correspondence with said rotor means in respective, opposite directions at nominally equivalent angular velocities, to move in respective revolvments in correspondence with the movement of said piston rod; respective means, articulatedly connecting the respective shuttle arms, nominally equally eccentrically, to respective ones of said rotor means, and said respective means, said rotor means, and said shuttle means being so constructed and arranged that the disposition and motion of said shuttle means throughout its travel is nominally in a reciprocating, right-angle, transverse plane with respect to said piston rod and also that said piston rod and said piston means coupled thereto reciprocate along and simultaneously, cyclically revolve in oscillatory movement about the axis of said piston rod, cylinder means circumscribing said piston means in operative relationship with respect thereto and having intake and exhaust ports so arranged as to register with said aperture means of said piston means at desired times to enable passage of fluid material therethrough, through said cylinder means and piston means, and thereby effect desired work; a lubricating coolant containing housing encasing said rotor means and said shuttle means; and means for progressively circulating said lubricating coolant from said housing through said rotor means, said shuttle means, and into said piston rod at said universal connections and through said piston rod in a double-backed path, in progression, back to said housing.

31. In a vacuum pump including a cylinder having porting ports longitudinally and radially spaced about a central region thereof, a piston operatively disposed in said cylinder and having porting aperture means longitudinally and radially spaced about a central portion thereof, and means for reciprocating and oscillating said piston coupled thereto, an improvement comprising means for circulating oil under pressure through said cylinder, said cylinder having at least one annular groove disposed in communication with said circulating means and about and always adjacent said piston at a cylinder area which is unswept by said piston's porting aperture means.

32. In a vacuum pump including a cylinder having porting ports longitudinally and radially spaced about a central region thereof, a piston operatively disposed in said cylinder and having porting aperture means longitudinally and radially spaced about a central portion thereof, and means for reciprocating and oscillating said piston coupled thereto, an improvement comprising means for providing an oil seal at the piston-cylinder juncture and for conducting oil to and for circulating said oil through said cylinder, said cylinder having at least one annular groove disposed in communication with said circulating means and about and always adjacent said piston at a cylinder area which is unswept by said piston's porting aperture means, said oil providing means also conducting away leakage media at said seal.

33. A motion transforming device including, in combination, a rod, a pair of rotors disposed equidistantly on opposite sides of said rod, having nominally coincident axes of revolution transverse to said rod and adapted for

revolvement thereabout in opposite directions and at equal angular velocities, shuttle means articulatedly mounted to and between said rotors at points of nominal equal eccentricity with respect to the latter, said shuttle means and said rod being coupled together in a universal connection and also being keyed together for mutual translation along and revolvement about the axis of said rod, and resilient means disposed between and engaging said shuttle means and said rod, said resilient means being spaced from said universal connection of said shuttle means and said rod.

34. A motion transforming device including, in combination, a rod, a pair of rotors disposed equidistantly on opposite sides of said rod, having nominally coincident axes of revolution transverse to said rod and adapted for revolvement thereabout in opposite directions and at equal angular velocities, shuttle means articulatedly mounted to and between said rotors at points of nominal equal eccentricity with respect to the latter, journal means respectively mounted in said rotors for articulatedly journaling said shuttle means, said shuttle means and said rod being coupled together in a universal connection and also being keyed together for mutual translation along and revolvement about the axis of said rod, a source of lubricating coolant, and means for circulating said lubricating coolant through a continuous circuit including said rotors, said journal means, said shuttle means and said rod, said circulating means comprising transverse passageways in each of said journal means for passing said lubricating coolant transversely through said journal means and into said shuttle means, and passageway means in said shuttle means progressively and sequentially communicating with said journal passageways, and wherein more specifically, said shuttle means is provided with oppositely extending arms, said journal means comprising respective spherical bearings individually having socket means and a ball universally mounted therewith and both provided with said passageways which intercommunicate with each other, said arms being respectively journaled within the balls of respective ones of said journal means and being movable therewithin in translation and revolvement directions, said passageway means comprising a plurality of apertures disposed in respective ring patterns about the respective arms of said shuttle means, which patterns are always operatively disposed within the balls of respective ones of said journal means, said passageways of each of said balls being disposed in an askew manner through each of said balls, originating at the ball periphery and divergently extending toward and terminating at the journal of said ball with a respective one of said shuttle arms in operative communication with said passageway means thereof, each of said balls at their shuttle arm journals being provided with at least one annular groove providing intercommunication between a plural number of said askew passageways communicating therewith, said socket means being provided with an inner annular groove, the originating extremities of said passageways of said balls being so constructed and arranged relative to said annular groove of said socket means as to sweep over said annular groove of said socket means so that at least one of them is in operative communication therewith at all times, and means for supplying lubricating coolant to said annular groove of said socket means.

35. A motion transforming device including, in combination, a rod, a pair of rotors disposed equidistantly on opposite sides of said rod, having nominally coincident axes of revolution transverse to said rod and adapted for revolvement thereabout in opposite directions and at equal angular velocities, shuttle means articulatedly mounted to and between said rotors at points of nominal equal eccentricity with respect to the latter, journal means

respectively mounted in said rotors for articulatedly journaling said shuttle means, said shuttle means and said rod being coupled together in a universal connection and also being keyed together for mutual translation along and revolvement about the axis of said rod, a source of lubricating coolant, and means for circulating said lubricating coolant through a continuous circuit including said rotors, said journal means, said shuttle means and said rod, said circulating means comprising transverse passageways in each of said journal means for passing said lubricating coolant transversely through said journal means and into said shuttle means, and passageway means in said shuttle means progressively and sequentially communicating with said journal passageways, and wherein more specifically, said shuttle means is provided with oppositely extending arms, said journal means comprising respective spherical bearings individually having socket means and a ball universally mounted therewith and both provided with said passageways which intercommunicate with each other, said arms being respectively journaled within the balls of respective ones of said journal means and being movable therewithin in translation and revolvement directions, said passageway means comprising a plurality of apertures disposed in respective ring patterns about the respective arms of said shuttle means, which patterns are always operatively disposed within the balls of respective ones of said journal means, said passageways of each of said balls being disposed in an askew manner through each of said balls, originating at the ball periphery and divergently extending toward and terminating at the journal of said ball with a respective one of said shuttle arms in operative communication with said passageway means thereof, each of said balls at their shuttle arm journals being provided with plural annular grooves providing intercommunication between respective sets of a plural number of said askew passageways communicating therewith, said socket means being provided with an innerannular groove, said passageways of said balls being so constructed and arranged relative to said annular groove of said socket means that said sets operatively continuously sweep over said annular groove of said socket means such that the originating extremity of at least one of the passageways of each of said sets is in communication with said annular groove of said socket means at all times, and means for supplying lubricating coolant to said annular groove of said socket means.
